BOTTLE FILLING MACHINE

Lewis E. Fagan, Chicago, and Albert B. Mojonnier,
 Park Ridge, Ill., assignors to Mojonnier Bros.
 Co., a corporation of Illinois

Application June 7, 1937, Serial No. 146,888

35 Claims. (Cl. 226—116)

The present invention relates to bottle filling machines generally and has to do more particularly with machines of this class wherein a vacuum is used to draw the liquid into the bottles or other receptacles which it is to fill.

The invention is embodied in a machine designed as an improvement upon the filling machine of our prior Patent No. 1,966,889, granted July 17, 1934.

One object of the invention is to so construct and arrange the various parts of the machine that they may be easily cleaned. In some instances this means separation and removal; in others accessibility.

Another object is to so construct the parts that the liquid will be handled with a minimum of admixture of air. This makes the machine useful in filling both light and heavy liquids, such as milk and other relatively light liquids on the one hand, and cream, other relatively heavy milk products, mayonnaise, mustard and the like on the other hand. These heavier liquids do not throw off the air once it is admixed, so readily as do the lighter liquids. Hence, if air can be kept from mixing with the liquid whether light or heavy, improved results may be had.

Another object is to give the bottle lifters a smooth action, free from unnecessary movements. This is done by a novel application of the actuating air, especially at the time the lifters are being lowered.

Another object is to improve the mechanism and filling heads so as to readily and effectively clear the latter of drip.

Another object is to produce a machine which will be simple and effective in operation, economical to manufacture and easily handled and repaired.

These and other objects and advantages of the invention will be more fully understood upon reference to the following detailed description taken in connection with the accompanying drawings, while the scope of the invention will be particularly pointed out in the appended claims.

In said description, milk will be taken as an illustrative liquid and bottles as illustrative containers. But it should be borne in mind that the invention may be used in connection with the filling of other liquids and substances into not only bottles but also other containers. And the claims should not be unduly limited in this respect.

In said drawings, Fig. 1 is a perspective view of a machine constructed and arranged in accordance with the present invention, the same being

shown also in conjunction with a capper of preferred construction; Fig. 2 is a partial sectional view of the upper portion of the filling machine shown in Fig. 1, the plane of section being indicated by the line 2—2 of Fig. 6; Fig. 3 is a similar section through the lower portion of the machine, the plane of section being indicated by the line 3—3 of Fig. 6; Fig. 4 is a plan view of a portion of the trap tank and associated valves and operating mechanism; Fig. 5 is a vertical section, 10 upon an enlarged scale, through the same trap tank and mechanism, the plane of section being indicated by the lines 5—5 of Figs. 4 and 6; Fig. 6 is a plan view of the lower portion of the machine, parts being shown in section, the position 15 of section being indicated by the line 6—6 of Fig. 2; Fig. 7 is a bottom plan view of the machine; Fig. 8 is a horizontal section taken near the bottom of the filling machine and showing a portion of the gearing and the air channels for 20 supplying air to the lifters and other mechanisms, the plane of section being approximately that indicated by the line 8—8 of Fig. 3; Figs. 9, 10, 11 and 12 are transverse sections through the air channels in the stator of the machine, the sections being indicated by the lines 9—9, 10—10, 11—11 and 12—12, respectively, of Fig. 8; Fig. 13 is a vertical section through a portion of the main and trap tanks, illustrating particularly the inlet control valve, the plane of section being indicated by the line 13—13 of Fig. 4; Fig. 14 is a similar section illustrating the outlet valve, the plane of section being indicated by the line 14—14 of Fig. 4; Fig. 15 is an exploded view of the main parts of the machine showing how they are separated for the purpose of cleaning, the parts being shown more or less diagrammatically; Fig. 16 is a vertical sectional view of one of the filling heads employed in the machine, the plane of section being indicated by the line 16—16 of Fig. 40 19; Fig. 17 is a perspective view of the same head with the resilient receptacle engaging cushion removed; Fig. 18 is a similar view with a portion of the cushion in place, the view being taken at a different angle and the cushion being shown in 45 central vertical section; Fig. 19 is a bottom plan view of the head illustrating the cushion in position and showing the relative positions of the filling and vacuum ports; Fig. 20 is a central vertical section through one of the bottle supports or 50 lifters of the filling machine; Fig. 21 is a horizontal sectional view through one of the lifters, the plane of section being indicated by the line 21—21 of Fig. 20; Fig. 22 is a central vertical section through the thrust bearing which carries the

central rotary column of the machine, the plane of section being indicated by the line 22—22 of Fig. 3; Fig. 23 is a side elevation of the trap tank, detached from the rest of the machine, illustrating particularly the air valve openings and the wall which forms the inlet channel or vestibule of the trap tank; Fig. 24 is a plan view of a portion of the carrier of the machine illustrating the manner of adjusting the inner and outer portions of the carrier relatively to each other; Fig. 25 is a vertical section through an oiling device used in supplying oil to the interior of the bottle lifters; Fig. 26 is a diagram of a pneumatic control system for operating certain parts of the machine in proper timed relation, certain structural parts being shown in sections indicated as follows: the stator ring on line a—a of Fig. 8, the electric switch box on line b—b of Fig. 7, and the butterfly valve casing on line c—c of Fig. 7; and Fig. 27 is a sectional view on an enlarged scale of a leak valve used in the control of the electric switch. Throughout these views like characters refer to like parts.

As previously indicated, the full machine illustrated in the drawings comprises a filling machine and a capping machine. These are both mounted on a base A. In brief, the filling machine comprises a stator and a rotor. The stator includes the base A and a ring-shaped bearing member A' which rests upon the base A, together with other non-rotary parts carried by these. The rotor includes a central column or stem B which extends down through the center of the bearing member A' and rests in a thrust bearing B' hung from the under side of the base A. The stem B is vertically adjustable with reference to the bearing A' and is held in adjusted positions by suitable latch mechanism B² associated in part with the column and in part with the bearing. The stem B carries a number of milk holding and controlling elements which move with the stem. Among these elements are a bottle carrier C; bottle lifters D located upon the carrier; a main tank E in which are located a float tank F; a trap tank G normally positioned in the upper portion of the main tank; filling heads H carried by and just outward of the main tank and in vertical alignment with the lifters D one head being vertically above each lifter; a dump tank J adapted to rest as a cover upon the upper edges of the main and trap tanks, and, through the agency of a cushioning ring K of rubber or like material, to seal off a vacuum chamber L lying just outward of the upper edge of the main tank and beneath the peripheral portion of the dump tank. The milk or other liquid to be filled into the bottles or like receptacles M, is deposited in the tank J. Where the same is brought into the tank through pipes, such as the piping N, a float control valve C is preferably employed to keep the liquid in the dump tank at a substantially constant level.

In operation, the milk passes from the dump tank J into the main tank E, the passage being controlled by the float F and its associated valve. Vacuum in the chamber L draws air through a vacuum passage in the head H, and, whenever a bottle is in position to be filled, the effect of the vacuum is to draw the air out of the bottle. Then because of the milk passage in the head H and its connection to the main tank E, into which milk has been fed, milk will be drawn from said tank E into the bottle. Although we say "draw" or "drawn" when describing this opera-

tion of the machine, yet it will be understood that in reality the milk is forced up from the tank E into the head H and bottle M by reason of the greater pressure of the air upon the milk in the tank than in the bottle. However, to use the more popular language seems desirable and so we shall continue to speak in that way. Obviously, when the bottle is filled, the lifter F withdraws the bottle from the filling head H and thus the vacuum is cut off. The shape of the head is such that any drippage that forms on it is drawn up through the vacuum passage into the chamber L. Furthermore, the milk in the milk passage on its way up to the bottle at the time the vacuum is broken, falls back into the tank E and thus helps to suck up the milk in the head near its milk outlet and bring it back into the main tank E. This syphoning of the milk into tank E is in addition to the drawing of the milk into the vacuum chamber L. Milk which is drawn up into the vacuum chamber is locked back again into the main tank E through the trap tank G. This locking of the accumulated milk through the trap tank is accomplished by regularly operated valve mechanism P. This mechanism includes two valves, one of which controls a passage between the vacuum chamber L and the trap tank G and the other of which controls a passage between the trap tank G and the main tank E. These valves are operated at regular intervals and when the passage between chamber L and tank G is open then the passage from tank G to tank E is closed. At this time the pressures in the trap tank G and the chamber L equalize and the resulting pressure is below normal. When thus equalized, accumulated milk in the chamber L will pass through the valve opening into the chamber G. In the alternate positions of the valves, the passage between chamber L and tank G is closed and that between tank G and tank E is open. When this occurs the air pressure within the trap tank G again changes to that within the tank E. At this time the milk in the tank G flows out into the tank E. It must be remembered that the lifters D bring the bottles M into contact with the heads H and remove them therefrom at proper times just, as in our aforesaid Patent No. 1,966,889 and as pointed out more fully hereinafter.

The capping machine may be of any preferred construction and in itself constitutes no part of the present invention. One like that disclosed in our aforesaid Patent No. 1,966,889 may be used. Or, again, one like that disclosed in our copending application Serial No. 146,809, filed June 7, 1937 and granted November 29, 1938 as United States Patent No. 2,138,271, may be used. The capper illustrated, namely, the capper Q, is like that disclosed in said latter patent. It is included in the general view of the drawings only because it forms part of the complete machine which has been built and operated and cannot very well be omitted from general views.

In addition to the filling and capping machines, we have also disclosed certain conveying elements T, by which the bottles are brought to the filling machine and conveyed from it to the capping machine, and then from the latter to a delivery point. These conveying features are similar to those disclosed in our aforesaid Patent No. 1,966,889. They will be discussed more fully hereinafter.

Furthermore, there is certain adjusting mechanism W by which the rotor of the machine may

be raised and lowered. Then, too, there are the driving motors X and Y and the associated suction pump Z.

Having set forth the general nature of our improved filling machine and its operation, attention may be directed more particularly to the details of its several parts.

The base A, in the present instance, is a casting of fairly regular outline provided with an upper floor 30 and a lower flange 31, both of which extend inwardly from a more or less vertical web 32. The floor 30 extends over the entire extent of the base except where it lies directly beneath the filling and capping machine rotors. At those points it is provided with circular openings for the reception of the rotary elements. The flange 31, on the contrary, extends only a short distance inward from the peripheral web 32. The particular arrangement of these various base parts is not a matter of great importance; different designers might desire different arrangements.

This base, or frame, is provided in the present instance with four legs 33 which are suitably secured to the lower flange 31 and provided at their lower ends with adjustable leveling screws 34. These screws preferably rest upon floor shoes 36. At their upper ends the screws 34 are threaded into tapped openings in the lower ends of the legs. Heads 35 formed upon the screws 34 enable them to be readily turned. By adjusting the screws 34, the position of the foot plates 36 may be varied with reference to the associated legs and in this way irregularities in the floor or foundation upon which the machine is positioned may be counteracted and the machine properly leveled. As clearly shown, particularly in Fig. 7, there is a pair of these legs at each end of the base, one pair being located beneath the filling machine and the other pair beneath the capping machine. Suitable machine screws 37 pass through flanges 38 at the upper ends of the legs 33 into widened portions 29 of the flange 31 of the frame and thus secure the legs to the frame.

The bearing member A', located upon the base A, includes an outer rim or ring 40, radial spokes 41 and a hub member 42. The rim or ring 40 is carried by the flange 31 of the base A. Interposed adjusting screws 43 furnish the points of support. As in the case of our prior Patent No. 1,966,889, there are three screws 43 and thus a three-point suspension is provided. Each of the screws 43 is furnished with a lock nut 39. The bearing A' is held down upon the base A, preferably by passing the screws 43 upward into threaded engagement with tapped openings in the under side of the ring 40. Once the screws 43 are properly positioned, the lock nuts 39 are set and the adjustment maintained. On the inner cylindrical surface of the hub 42 is a sleeve 44 of suitable bearing metal. This is necessary because the central column B and associated parts rotate within the bearing formed by the hub 42 and the associated bearing sleeve 44.

Turning now to the hub structure of the carrier C, it will be seen that the same comprises a bearing sleeve 45, which comes into direct wearing engagement with the fixed wearing sleeve 44, a flange 46 on the sleeve 45 and an associated outer ring 47. The ring 47 is secured in place beneath the flange 46 by screws 48 which pass through the flange into threaded engagement with tapped openings in the ring 47. Just inward of the sleeve 45 is an additional wearing sleeve 49 of suitable metal. The latter sleeve en-

gages the column or stem B of the machine. Although the carrier and its hub rotate with the column B, yet the latter is vertically adjustable relative to the former and therefore it is desirable to employ the sleeve 49 of softer bearing material.

Before referring to other parts of the carrier C, it may be well to consider the central column B, especially since it is associated with the hub structure of the carrier which we have just been considering, and is vertically adjustable relative to the same. Upon examination, it will be noted that the column B includes an outer tube 50 and an inner tube 51. The outer tube has a number of circumferential kerfs or grooves 52 which cooperate with parts of the catch mechanism B² in holding the column in its different adjusted positions relative to the bearing member A' and the carrier C. The two tubes 50 and 51 are secured together by centering bushings 53 and 54, located, the one at the upper end of the tube 50, and the other at its lower end. The bushings 53 and 54 have threaded engagement with the tube 51. They also have shoulders which bear against the ends of the tube 50 when the bushings 53 are screwed home.

From what has been said, it will be seen that the member A' forms part of the stator or fixed part of the machine while the other parts which are mounted within the hub 42 of the bearing member A' are rotatable and, therefore, form parts of the rotor. In this connection, it should be noted that the column B is not only rotatable with the hub of the carrier C but it is capable of vertical adjustment with reference to both said carrier and the bearing member A'.

Turning now to a consideration of the catch mechanism B², by which the column B is held in its different vertical positions, it will be noted that a catch ring 55 carried by and rotated with the hub of the carrier cooperates with the grooves 52 in the outer tube 50 of the column B to hold the latter in its different vertical adjustments. In order that the catching edge of the ring 55 may reach the grooves 52, it is necessary that the sleeve 45 be provided with a horizontal slot 45^a. This slot extends about two-thirds of the way around the sleeve, namely, from the point m to the point n as the parts are viewed in Fig. 8. The wearing sleeve 49 is also, of course, similarly slotted. It will also be noted that each groove corresponds to a different vertical setting of the column. The ring 55 has a large central opening, as clearly shown in Fig. 8. By horizontal movement, the edge of the ring at the left, as the parts are shown in Fig. 3, may be moved through the slot 45^a in sleeve 45 and the cooperating registering slot in the wearing sleeve 49 on into the grooves 52 for the different vertical settings of the column. These vertical adjustments are made for the purpose of raising the upper portion of the machine to different elevations relative to the carrier C, and thus to suit the machine to operating with bottles or other receptacles of different heights. Obviously, a suitable number of grooves 52 should be provided to care for all the different settings of the machine which are required in service.

It will also be noted that the catch ring 55 is provided with a block 56 which is suitably secured to the ring, as by means of one or more bolts 154 having suitable nuts, as shown. The block 56 is radially apertured for the passage of a rod or stem 57 which is firmly seated and retained at one end within a recess formed in the

ring 47. A compression spring 58 acts between the block 56 on the one hand and the ring 47 on the other to move the catch ring 55, to which the block 56 is fixed, into groove-engaging position. Such a position is illustrated in Fig. 3. As before noted, the ring 55 and the associated parts rotate with the hub of the carrier during the normal operation of the machine. Since this is so, some special provision must be made for actuating the ring when it is desired to change the vertical adjustment of the column B.

For the purpose of actuating the catch ring 55 from the outside of the machine, it will suffice to locate actuating mechanism at one point in the stator and then when the rotor is stopped, move it by hand until the appropriate part of the catch ring 55 is in position to be actuated by the fixed control mechanism. This is a simple operation since there is no need of keeping the carrier rotating when making the adjustment.

The mechanism for actuating the catch ring 55 includes a reciprocating rod 61 which carries a block 62. The latter has an upwardly extending projection 63 which is in position to engage the catch ring 55 at a point adjacent to the block 56 whenever the rotary elements of the machine are circumferentially positioned so as to bring the block 62 and projection 63 into alignment. The rod 61 is provided with a shoulder 64 which presses against a corresponding shoulder provided in a bore of the block 62 in which the rod 61 is located. A pin 65, or like device, is used to hold the rod against withdrawal from the block 62. The rod 61 is provided with bearings 66 and 67 located in an auxiliary frame 68 secured to the flange 32 of the frame A by suitable screws 69. Within the member 68 is an enlarged bore or chamber 72 through which the rod 61 extends. The bearing 66 is formed by a sleeve located at one end of the chamber 72 and the bearing 67 is provided by the aperture in a plug threaded into the other end of the chamber. The rod 61 carries a flange 73 or equivalent device against which one end of a compression spring 74 presses. The other end of the spring presses against the bearing member 66 and thus there is a constant tendency exerted to move the rod 61 into its outermost position. Whenever it is in this position, the catch ring engaging lug 63 will be free of engagement with the catch ring 55 as the latter rotates. Obviously, when the rotary elements of the machine are properly set, any inward thrust of the rod 61 would cause the projection 63 to engage the catch ring 55 at a point adjacent to the block 56 and, then, when the stem B is raised slightly to free the ring, the latter may be moved out of groove-engaging position and it will be possible then to vertically adjust the stem as desired. Of course, the positions of adjustment are limited to the number and positions of the various grooves 52. Once the machine has been vertically adjusted to the desired setting, corresponding to a groove 52, the catch ring 55 must be allowed to respond to the action of its spring 58 and thus be brought into groove engagement. Such a movement of the catching ring 55 will be permitted whenever spring 74 associated with the actuating rod 61 has been allowed to move the latter to its normal outermost position.

The rod 61 may be shifted against the compression of its spring 74 by any suitable means. Preferably an actuating lever 75 is pivoted at 76 to one or more lugs 77 which project from the base A at a point adjacent to the outer end of

the rod 61. Normally the outer end of the rod presses against the end 78 of the lever 75 and holds the latter in its normal position. To shift the rod 61 inward to operate the catch plate 55, when the parts are properly set, it is only necessary to rock the lever 75 about its pivot 76 and thereby force the end or foot 78 of the lever against the end of the rod 61 and move the latter inward to bring about the action previously described.

As shown more particularly in Fig. 8, the upper edge of the ring 40 of the bearing member A' is provided with two continuous grooves 80 and 81. Both grooves are circular. The members A and A' are, when once adjusted to each other, relatively fixed and constitute the stator of the machine. In one sense they form its base. The outer groove 80 of the stator is divided into two sections or segments by plugs 82 and 83 located at approximately diametrically opposite points. The portion of the groove 80 at the left, as the parts are viewed in Fig. 8, constitutes a segmental passage which is supplied with air under pressure at all times during the operation of the machine. On the other hand, the portion of the groove 80 at the right, as viewed in the same figure, is connected to atmosphere at all times. Both these sections of the groove 80 are chambers or passages which cooperate with the carrier C in providing compressed air supply and exhaust connection with the pneumatically operated mechanism P by which the valves of the trap tank is utilized in passing milk from the vacuum chamber L through the trap tank G to the main tank E. The upper bearing edge of the stator ring 40 and the cooperating ported under side of the carrier C thus constitute a distributing air valve for controlling the operations of mechanisms on the rotor.

When it comes to the inner groove 81 in the stator ring 40, we have provided four segments. These have connections to a compressed air supply and to atmosphere. Through their agency, the bottle supports or lifters D are raised and lowered and thus the bottles are raised and lowered at the proper points in their rotation. There is also a short section to be used in supplying lubricating oil to the interiors of the lifters. Four plugs 84, 85, 86 and 87 provide these four sections. The section between plugs 84 and 85 is a short section and one used in applying the oil. The section between plugs 85 and 86 is a long section and is one by which compressed air is supplied to the lifters to raise them and the bottles upon them. The section between plugs 86 and 87 is a short exhaust section and allows for the lowering of the lifter. And the last section, namely that between plugs 87 and 84, is a relatively long exhaust section and while the lifters travel over it they remain in their lowermost position. Really the travel between plugs 86 and 84 is over an exhaust channel, but the plug 87 is inserted so that any sudden discharge of air from any given lifter just after it has passed plug 86, will not kick up the lifter or lifters just in advance of it. Thus, any possible dancing of the lifters by reason of a sudden release of air from any one of them is prevented.

It will be apparent that the compressed air may be supplied from any suitable source and piped to the inlet ports 88 and 89. Thus, supply pipes 90, 91 lead respectively to the ports 88 and 89. In the case of the left hand segment of the outer groove 80, as the parts are viewed in Fig. 8, compressed air may also be supplied through

pipes, but, preferably, the connection is made by piercing the partition between the two grooves by an opening 92. When it comes to the exhaust, suitable exhaust ports 93 and 94 are provided and there is a communicating opening 95 between the grooves. The ports 93 and 94 may be provided with exhaust pipes, if desired, as shown by short lengths 96 and 97, communicating with said ports.

D When it comes to injecting oil up into the interiors of the lifters, any suitable device for combined air and oil and delivering them to the port 88 may be employed. Such devices are well known. One is illustrated in Fig. 25 and will be described more fully hereinafter.

Because of the importance of having the various sections of the channels 80 and 81 properly positioned with reference to the cooperating parts, in order to obtain proper operation, some provision must be made for an accurate rotary adjustment of the ring 40 about the central stem B. To provide for such rotary adjustment, the lower flange 31 of the base A is provided with a pair of lugs 98 which lie on opposite sides of one of the spokes 41. Through threaded openings in the lugs 98, oppositely positioned screws 99 extend and are brought into engagement with opposite sides of the interposed spoke 41. By unscrewing one of the screws and screwing down on the other, an accurate positioning of the spoke 41 may be had. This means an accurate rotary positioning of the bearing member B'. When this bearing has been once set in proper rotary position, then lock nuts 100 upon the screws 99 may be turned down against the lugs 98 to hold the screws against dislodgement.

The bottle carrier C has an outer annular body 101 connected by spokes 102 to the central hub ring 47 which, as before noted, is secured to the sleeve 45 and is free to rotate with reference to the hub 42 of the circular bearing A'. The inner portion of the annular body 101 is provided with a central apron 103 which extends into the vicinity of the hub members 45 and 47. The apron 103 is secured to the ring 101 in any desired way. Preferably, this is accomplished by one or more screws 104. Each screw 104 passes through a short circumferential slot 59 in a bossed portion of the apron 103, shown in Figs. 2 and 24, into threaded engagement with a tapped opening in the adjacent portion of the carrier ring 101. By means of the slots 59, the two members 101 and 103 of the carrier C can be adjusted about the axis of the machine to bring the filling heads H into proper vertical alignment with the bottle lifters D. When adjusted, the screws 104 may be screwed home and the two parts of the carrier held in adjusted position. To adjust these parts 101 and 103 nicely, the apron 103 is provided with two spaced lugs 60 located near its periphery. Between these lugs 60, there is a notched opening 70 through which a stud post 79 is adapted to extend. This post is set in a vertical opening in a boss or lug 139 which extends inwardly from the carrier ring 101. A set screw 140 serves to hold the post 79 in proper position. The upper end of the post 79 enters the space 70 between the lugs 60. Adjusting screws 141 are threaded through threaded openings in the lugs 60 and abut against opposite sides of the post 79 to hold the two carrier members 101 and 103 in proper adjusted position. By letting off on either screw and screwing up on the other, the adjustment may be varied as is obvious.

As clearly shown, the lower portion of the car-

rier ring member 101 has connected to it a toothed ring 105. Suitable screws 106 pass through the ring 105 into threaded engagement with the body of the member 101. This toothed ring 105, when mounted on the carrier, constitutes a gear wheel 5 by which the carrier is rotated through the agency of gearing which will be pointed out more fully hereinafter.

The carrier ring 101 is provided with the bottle supports, which, in this embodiment, takes the form of lifters D, for raising and lowering the bottles M, into and out of engagement with the filling heads H. The structure of these lifters is clearly disclosed in our aforesaid Patent No. 1,966,889, and also in Figs. 20 and 21 herein. The annular body 101 is provided with a number of vertical posts 107. Each post 107 is bored out at its center to provide a chamber or well 108. In this well a dash pot piston 109 is adapted to travel. This piston is carried at the lower end of a piston rod 110, the piston and rod being secured together by a transverse pin 111. The rod 110 is provided with oppositely disposed grooves 112 which grooves cooperate with keys 113 in guiding the rod 110 and prevent rotation of the rod. The keys 113 are secured on the inner side of the upper end of a tubular sleeve 114 which fits down into the well 108 in the post 107. The sleeve 114 is secured against removal by a set screw 115 which is preferably covered by a cap nut 116 fitting down upon a gasket 117 when in secured position. As clearly shown, the inner end of the screw 115 enters an opening in the wall of the sleeve 114. The keys 113 are narrow blocks which are secured to the sleeve 114 by any suitable means such as the rivets 118. In the specific construction shown, the upper end of the tubular sleeve 114 is provided with a thickened portion or ledge 119 which extends inward and forms an underlying abutment. This ledge is slotted for receipt of the keys 113 and the latter are held in place by the rivets 118 as just noted.

With this construction, it will be seen that, when the sleeve 114 is in place in the bore in the post 107 and the keys 113 enter the slots 112, then the piston rod 110 will be free to move up and down but will be held against rotation by the keys 113 in the slots 112. A coiled compression spring 120 acts between the upper side of the piston 109 and the under side of the underlying abutment 119, and, since the sleeve 114 is fixed in the post 107 by the screw 115, the action of the spring is to hold the piston 109 normally in the bottom of the well 108. The upper end of the piston 110 is secured to the lifter head 121. The latter is preferably provided with a tubular sleeve 122 at its center, into which the end of the rod 110 enters, and to which it is secured by a transverse pin 123. The head 121 also carries near its periphery another annular flange 124 to which the skirt 125 of the lifter is suitably secured as by soldering, indicated at the points 126. The skirt 125 is in fact a cylindrical sleeve which passes down over the outside of the post 107. The upper end of the post is provided with suitable packing in the form of a cupped leather 127 which is secured between retaining rings 128 and 129 by a plurality of screws 130 which pass down through the rings and intervening leather into threaded engagement with tapped openings in the upper end of the post 107.

The packing 127 thus provides a reasonably air tight connection, and compressed air which is admitted through the tubular passages 131, 132, and 133 will be retained within the space above 75

the packing 127 and beneath the head 121 and by its force press the head 121 upward against the downward pressure exerted by the spring 120. When the compressed air is no longer supplied but the passage 133 is open to atmosphere, then the compressed air will pass out of the chamber beneath the lifter head 121 and the latter will be returned to its normal position by the spring 120. In order to suitably retard the action of the spring, the well 108 is partially filled with oil or other liquid which normally rests approximately at the level indicated at 134. The upward movement of the lifter head will be retarded by the spring 120 and the oil contained in the well 108. Likewise when the return movement of the head occurs, under the downward pressure of the spring 120, the retarding effect of the oil in the well will also be brought into service. As the piston 109 passes up or down, the oil will 10 find its way past the piston, both through the openings 135 through the piston and, to some extent, through the space between the piston and the associated cylindrical wall. In other words, the lifter head is raised by compressed air and lowered by gravity and spring pressure, the oil meanwhile retarding the movement in both directions. In this connection it may be pointed out that the lower end of the passage 133 terminates in a port 137 in the annular face 136 in 20 the under side of the carrier C.

As illustrated more particularly in Fig. 3, the underneath bearing face 136 on the rotor rests upon and engages the upper bearing face on the stator ring 40. When so positioned, the port 137 of the passage 133 cooperates with the inner channel 81 of the ring. This means that, as the lifters are rotated by the travel of the carrier ring 101 over the fixed ring 40, the port 137 will be brought into communication with the compressed air supply during part of each rotation and into communication with atmosphere during another part of each rotation. The segment covered during the communication with the compressed air supply is a long one, existing while the port 137 passes from plug 84 over plug 85 and on to plug 86. Similarly the segment allotted to the atmospheric connection is relatively short, existing while the port 137 passes from plug 86 over plug 87 and on to plug 84.

In Fig. 8 where the grooves 80 and 81 of the stator are most clearly shown, the rotor will travel clockwise, as indicated by the arrow. Obviously, while compressed air is being applied to a particular lifter D, its head 121 will be thrust upward and maintained in its uppermost position. On the other hand, as soon as the lifter is brought into that portion of its travel wherein air at atmospheric pressure only is available, then the head of the lifter will return to normal position and remain there throughout the balance of the cycle. Obviously, as each lifter passes over that portion of the groove 81 which lies between the plugs 84 and 85, oil laden air will pass up into the interior of the lifter to a point above the cup leather 127 and serve to lubricate the parts available to the oil when liberated in that location.

It may be noted at this point that the upper surface of each lifter head 121 is provided with a wear plate 138 which is secured to the head by suitable screws 139. As these plates become worn they may be replaced so as to maintain accuracy of adjustment with reference to the shifting of the bottles into proper filling engagement with the filler heads H.

Now, in addition to the port 137 and the associated passages 133, 132 and 130, by which actuating air for the lifters D is provided, there being one such port and set of passages for each lifter, the outer ring 101 of the carrier is provided with a single port and set of passages which control the flow of air to the valve mechanism P carried by the rotor. By reference to Figs. 3 and 5, the path for this flow of air may be readily traced. In line with the outer stator groove 80 is a port 142 located at the lower end of a passage 143 which connects with a short horizontal passage 144. The latter is provided with a pipe elbow 145 and to this is attached one end of a flexible tube 146 which has a certain amount of slack in its length to provide for adjustments when the upper portion of the rotor is elevated by raising the central column B. The slack portion of the tube 146 rests upon a supporting plate 147 carried by the carrier ring 101. The other end of the tube 146 is passed up through a tubular guide 148, which cooperates with other guides 149, to be hereinafter referred to when describing the mountings of the main tank E. The tubular guide 148, which is carried by the apron 103 of the carrier C, telescopes with a sleeve 150 which is carried by the main tank E of the rotor. The flexible tube 146 passes up through these telescoping tubes 148 and 150, and is fitted at its upper end to a head 151 located in the upper end 20 of the sleeve 150. Suitable passages 152 within the head and a short length of pipe 153 place the tube 146 into communication with the bellows fitting of the valve operating apparatus P. The effect of the supply and withdrawal of the compressed air coming from groove 80 in the stator to this bellows and the associated mechanism need not be taken up at present. That action can be deferred until the latter apparatus be taken up for detailed description.

The main tank E, considered apart from the covering dump tank J, is an open-topped tank. It comprises a cylindrical wall 158 and a dished bottom 159 which are suitably secured together at their meeting edges. Commonly the wall 158 and bottom 159 are welded together, as indicated at 160. The bottom 159 carries a series of bolts 161 which are spaced apart around its periphery. Each bolt is fixedly secured to the bottom 159, preferably by welding. When assembling the parts, the bolts 161 are passed down through openings in the bowl 163 near its periphery. Cap nuts 162 upon the ends of the bolts 161 secure the tank and bowl together. This bowl is a casting which includes a tubular member 164 which functionally forms a continuation of the central tube 51. A washer 165 is positioned between the meeting ends of the tube 51 and the member 164. The tubular member 164 extends laterally to a point just beyond the periphery of the tank wall 158 and is there provided on its upper side with an opening for the reception of a removable vacuum pipe 166. Suitable packing and a packing gland 167 serve to make a reasonably air-tight joint. As clearly shown, the pipe or tube 166 extends into the interior of an inverted cup 157 formed on the bottom 168 of the dump tank J. The interior of the cup 157 is in direct communication with the vacuum chamber L when the parts are assembled. In practice the tank E rests upon the central column B. The two tubular members 164 and 51 are brought into vertical alignment and the former rests upon the latter, preferably with the washer 165 in between. This washer 165 is preferably composed of soft packing material. 75

1.16

7

In the embodiment shown, the washer 165 is held in place preferably by a rim 169 formed at the upper end of the tube 51. In some instances the metal faces of the tube 51 and the member 164 may meet without the intervention of the washer. Where a washer is used any desired way of holding it in place may be employed.

Since the bearing furnished by the faces of the members 51 and 164 is relatively small in contact area, it is necessary to provide other holding means to maintain the tank E in its central position over the column B. The aforesaid posts 148 and 149 serve this purpose. As before pointed out, the post 148 is tubular and carries the flexible air tube 146. The posts 149 are preferably solid as shown, although they might be tubular also, if desired. All these guide posts are preferably mounted in the same way. It will suffice then to refer to the mounting of the tubular post 148, the mounting of which is shown in detail in Fig. 2. As there shown, the post 148 passes through an opening in the apron 103 near its periphery and is held in place therein by a set screw 170. Three guide posts 148, 149 are shown although, obviously, the number may be increased if desired. The manner of mounting the posts in the carrier member 103 may be varied but it is essential, however, that the posts guide and maintain the main tank E in its central position. In order to provide a proper guiding contact between the tank E and the posts 148, 149, the bowl 163, upon which the bottom 159 of the tank rests, is provided at points in radial alignment with the guide posts, with guide shoes 173. These are concavely curved on their outer surfaces to properly fit the cylindrical surfaces of the posts and each is provided with a stem which enters a socket 174 formed in the periphery of the bowl 163. The stem, when once positioned is held firmly in place by a set screw 175 which is threaded into an opening in the adjacent portion of the bowl and when screwed home presses firmly against the stem of the shoe. It will be obvious that with three or more guide posts 148, 149 in association with the cooperating shoes 173, the main tank E and the structure which it supports will be firmly held in central position and this will be true even when all the parts are rotating as will be the case when the machine is in operation. The bottom 159 of the tank E is provided with a drain pipe 176 in which is located a drain valve 177. As clearly shown, the bottom 159 of the tank is dished and the drain pipe 176 is located at the lowest point of the tank. In operation the drain valve 177 is normally in closed position, but, when it is necessary to empty the tank, then the same may be thrown into its open position and the liquid contents of the tank E drained off.

The outer wall 158 of the tank E is pierced by a number of milk supply tubes 178. These tubes terminate at their inner ends near the bottom 159 of the tank, and, as shown, extend upward and outward into communication with the filling heads H, there being one tube 178 for each filling head. The tubes 178 are preferably reinforced by sleeves 179 at the points where they pass through the tank wall 158. The tube 178, sleeve 179 and wall 158, in each instance, are all firmly and permanently secured together as by welding. Thus the several tubes 178 are symmetrically disposed about the tank axis and extend from points well below the milk level 180 to the heads H which are well above that level.

It should be noted, while considering the milk

tubes 178, that the lower ends of these tubes are cut off along a horizontal plane. This makes all points of the lower end of each pipe an equal distance from the milk level. In other words, each point in each pipe inlet is subjected to the same head of liquid pressure. Thus, the flow of the incoming milk, in the case of each tube 178, is the same at all points around the periphery of the inlet opening. This insures quieter action of the milk, which is much desired. It should also be noted in this connection that the milk is withdrawn from the lower part of the holding tank E. In this way there is a withdrawing of milk independently of foam which, if present, lies near the top of the tank.

Within the main tank E are the float tank F and the trap tank G. The float tank comprises a top 184, a bottom 185 and an outer wall 186. In the embodiment shown the latter is conical in its lower portion and cylindrical in its upper portion. Besides these outer walls, is an inner tubular wall 187 which joins the top 184 and the bottom 185 and forms through its center a tubular passage for a cooperating feed pipe 188. The latter, sometimes called the milk pipe, extends down through the tubular space formed by the wall 187 and is provided at its lower end with a valve seat 189. The latter takes the form of a short tube which is inserted in the lower end of the milk pipe and welded or otherwise secured therein.

On the bottom of the tank F is a yoke 190 which is secured at its ends to the bottom 185 and provided at the center with a boss 191 which is apertured or socketed for the reception of the stem 192 of a disk valve 193. The latter, as clearly shown, is of sufficient size to properly seat itself upon the seat 189 when the two are brought together. The tank which carries the valve 193, being a float tank, normally rides on the body of milk carried in the main tank E. When the valve is open, as it is in the position shown in Fig. 2, milk travels from the dump tank J down through the feed pipe 188 into the main tank E. This travel continues until the milk level 180 in the main tank rises sufficiently to cause the float to bring the valve 193 into engagement with the valve seat 189. As soon as the milk level 180 drops, as it will do by reason of the removal of the milk from the tank E, the float tank F will drop and, as it does so, it will open the valve 193, and, as a result, more milk will flow into the main tank. In order to reduce the friction between the exterior of the liquid supply pipe 188 and the interior wall 187 of the float F, said wall is provided with two annular rings 194 which are formed by pressing the metal inward toward the axial center of the tank. Such protruding portions are the only portions which engage the feed pipe 188, and, thus, the friction between the float and the tube 188 is greatly reduced. Thus, we see, the tank E is a liquid container adapted to hold liquid at a level below the level of the filling heads H.

The trap tank G is made up of a cylindrical wall 198 and a dished bottom 199. The latter, as clearly shown, is bent convexly upward so as to drain liquid therein toward the periphery of the tank. The center of the bottom 199 is apertured for the passage of the feed pipe 188 and said pipe is firmly secured therein by welding or otherwise, and, preferably, is provided with reinforcing rings 200 which form part of a stout connection between the pipe and the tank bottom.

At this point, it may be well to notice the

connection formed between the upper end of the feed pipe 188 and the bottom 168 of the dump tank J. It will be seen that the latter is provided with a nozzle 201 and that the upper end of the pipe 188 passes into this nozzle. Within the nozzle is a rubber ring 202 which is shaped to fit over a flange 203 formed on the inner wall of the nozzle 201. The ring 202 is engaged by the upper end of the feed pipe 188 when the parts are in assembled position and a liquid tight joint is thereby provided. This joint is also reasonably air-tight since at certain times in the operation of the machine the interior of the trap tank G will contain air at vacuum or partial vacuum pressures. As clearly shown, the upper end of the milk pipe 188 is slightly contracted and thus a wedging fit is made against the rubber ring 202, when the parts are set in final position.

As clearly shown, the upper edges of the walls 20 of the main and trap tanks terminate at about equal distances from the dump tank bottom 168. To make a tight joint at this point, the rubber ring K is provided. This has substantially the same thickness throughout, with grooves or depressions 203a on its under side for receiving the edges of the tank walls 158 and 198. As previously pointed out, the valve actuating mechanism P includes two valves, an inlet valve 204 and an outlet valve 205. These are shown in detail in Figs. 4, 13 and 14, respectively. Since the inlet valve 204 is intended to admit air below normal atmospheric pressure into the trap tank G from the vacuum chamber L, it is necessary to provide an air-tight passage for the purpose. Such a passage is provided by surrounding the valve opening 206 with a wall 215. This wall is secured to the trap tank wall 198 and extends into close proximity to the main tank wall 158 when the parts are assembled. An opening 207 in the latter wall within the enclosure formed by the wall 215 completes the passage. In order to provide for a reasonably air-tight connection between this wall 215 and the adjacent wall 158, a rubber ring 208 is provided. This ring has on its inner face a depression 209 and thus enables the ring to be fitted carefully upon the edge of the wall 215. When the parts are assembled, the contact is made as shown in Fig. 13.

The trap tank G is supported in its proper vertical position by pins 210, 211, preferably four in number, which extend inward from the wall 158 of the main tank E. These pins are reduced in diameter at their outer ends and these reduced ends pass through openings in the wall 158. Preferably the pins 210, 211 are shouldered so as to fit against the inner face of the wall and the outer reduced portions are threaded in each instance for the reception of a cap nut 212, somewhat after the manner of the bolts 161 and nuts 162, previously mentioned. The pin 210 is in the vicinity of the valves 204 and 205 while the pins 211 are more distant from these valves. The pins 211 are provided in each instance with an inclined nub or ridge 213 which extends inward and downward so that when the trap tank G is pressed down into the main tank into position on the pins, the gasket ring 208, previously described, will be forced tightly against the adjacent tank wall 158 and a tight joint thereby be provided between the walls 158 and 215, where the rubber ring 208 is located.

Turning now to a consideration of the filler heads H associated with the outer ends of the supply pipes 178, it will be noted that these heads in general are similar in construction to those

illustrated in Fagan's Patent No. 1,929,736, granted October 10, 1933. There are some differences, however, which are of genuine importance because the present head has been developed to deal with liquids of greater density and viscosity and to prevent, as far as possible, the admixture of air. The improved filler head is illustrated in detail in Figs. 16 to 19, inclusive. As there shown, it comprises a body 217 of sufficient lateral extent to close the top of the bottle 10 or other receptacle to be filled. Through this head extends a downwardly inclined milk supply passage 218, terminating in a milk supply port 219. Likewise, through the head 217 extends a vacuum passage, terminating in a vacuum port 15 221. It will be noted that the port 221 is positioned in a face 222 which is practically horizontal and forms the lowest point of the head. Surrounding this face 222 is a more or less conical face 223, which extends from the apex face 222 20 outward and upward. The milk port 219 terminates in this inclined more or less conical face 223. The pipe 178 communicates with an apertured branch 224 which forms part of the body 217 but extends away from the same at an angle, 25 all as clearly illustrated. The angle is that which lies between the inclined supply pipe 178 and a vertical line. This is necessary because the head 217 must have a vertical axis. Such positioning of the head makes the 30 apex face 222 practically horizontal, as previously stated. The branch 224 is suitably bored out to receive the end of the pipe 178 which is preferably welded in place. The upper end of the branch 224 is open except for a plug 225 35 which closes the end of the passage when the machine is in service. It will be seen that when the plug 225 is removed, a swab rod or other cleaning device may be used to wash out and thoroughly cleanse the interior of the associated 40 tube 178. The milk passage 218 communicates at its upper end with the interior of the bore formed in the branch 224. Thus, milk ascending by way of the pipe 178 will pass into the supply passage 218 and be delivered at the port 219. 45 The upper end of the vacuum passage 220 opens out into the interior of the vacuum chamber L. The upper end of the body 217 passes through an opening in the lower wall 226 of the vacuum chamber L and is secured thereto in any suitable 50 way, as by welding. The vacuum passage 220 has an upper portion 227 of constant diameter and a lower portion 228 in which the diameter varies, the portion 228, as illustrated, has a downwardly converging conical wall. It will be noted, 55 too, that the diameter of the port 221 is considerably less than the diameter of the port 219. The axis of the milk passage 218 is also inclined to the vertical just enough to deliver the milk from the port 219 into a milk bottle against its side wall and thus cut down to a minimum the admixture of air due to the passage of the milk from the head into the bottle.

The lower end of the body 217 is recessed around its periphery for the reception of an irregularly shaped packing or cushion 229 of rubber or like material which forms the member which contacts with the bottle or other receptacle. The periphery of the rubber 229 is turned upwards with a lip 230 so as to provide a gutter for 70 the accumulation of liquid which might pass down from the outside of the head. This gutter has an outlet 231 which is formed by cutting away a portion of the lip 230. This enables the liquid which accumulates in the gutter to flow off. The 75

rubber ring 229 also has an outer portion 232 which passes down on the outside of the bottle or receptacle. It also has an inner flange 233 which passes down more or less into the top of the bottle or like receptacle. The annular flange 233 extends downward over the head nozzle into proximity to its lowest point. The head itself is shaped so as to receive the ring 229 with its irregularities. At one point near its periphery 5 the head is provided with a depression 234. This is made for the purpose of receiving a nub or projection 235 on the rubber ring 229 so as to properly position the ring upon the head.

The head H in its entirety includes the body 217 10 of metal and the ring 229 of rubber. When these two parts are assembled they provide an outer receptacle-engaging portion, lying between and including the flanges 232 and 233, and a central nozzle portion, lying inward of the flange 233.

20 In operation, as previously indicated, the vacuum in chamber L will, when a bottle or other receptacle is in receiving position, cause such a change in pressure as to bring about a travel of milk from the main tank E up through the associated tube 178 and passage 224, both passages being upwardly extending into the downwardly extending passage 218. When the bottle or other receptacle is filled and the vacuum is broken, there will be a flow of air up through the 25 vacuum passage 220. At the same time the milk which has been drawn up in the tube 178 on its way to the head, will fall back again into the tank E. Such downward flow of the milk in the tube will draw air up into the milk passages in 30 the head and into the tube. This upward flow of air in the milk passages and the rush of atmospheric air into the vacuum passage 220 in the same head will carry off drippage from the nozzle of the head. The syphoning action in the milk 35 passages, on the one hand, will clear the end surfaces of the nozzle adjacent to the milk port 219 and also the inner surfaces of the upwardly extending milk passage 218. The vacuum pull, on the other hand, will clear the surfaces adjacent to the port 221 and will draw any milk in the 40 vacuum passage 220 up into the vacuum chamber L. This double action (syphoning and vacuum pull) in removing drippage has given very satisfactory results in practice. Of course, if the 45 bottles should be left for a longer time than sufficient to fill them, then the surplus milk would be drawn up into the vacuum chamber L and locked back through the trap tank G into the main tank E. The flow of milk over this cyclic 50 path is what is called recirculation. If each bottle were just filled each time and no milk were drawn up into chamber L, then there would be no recirculation, but this is not feasible because it is necessary to draw off the foam and air from the 55 top of each bottle. This means that in practice some milk will be drawn off too. Hence there is liquid for recirculation. It is desirable, of course, to keep the recirculation at a minimum in order to keep the milk as quiet as possible.

60 Passing now to a consideration of the dump tank J, it will be noted that the bottom 168 of the same constitutes a cover for the main tank E and the trap tank G. As before noted, the closure is made tight by reason of the resilient cushioning ring K. This tank is provided with a top 240 which is similar in curvature to the bottom 168 but reversely curved. The bottom 168 and the top 240 are connected by a peripheral wall portion 241. These portions of the tank 65 70 75 may be made up by uniting different stamped

sheets, by welding or otherwise, so as to give the shape indicated. The top 240 of the tank is provided with openings 242, preferably three in number. These are surrounded by flanges, and caps, such as the cap 244, are used to cover the openings, all as clearly shown. In practice the piping N and float valve mechanism O may, or may not, be employed. When not employed, it would not be necessary to leave an opening in the center of the top 240 for the passage of the 10 piping. Where these parts are omitted the milk or other liquid is poured into the tank through the openings 242.

As before indicated, the vacuum chamber L surrounds the main tank E, just below the outer edge of the bottom 168 of the dump tank J. The vacuum chamber L has for its enclosing walls, the upper portion of the main tank wall 158, the adjacent peripheral portion of the bottom 168 of the tank J and an extra sheet forming a bottom 20 226 and an upwardly extending outer wall 246. The outer wall 246 is in substantial vertical alignment with the outer wall 241 of the tank J when the latter tank is in position. At such times the tank J is held in place by suitable straps 247, 25 each of which is apertured at its upper end so as to pass each over a hook 248, secured to the wall 241 of the tank J, by any suitable means as, for example, by a rivet 249. The lower end of each strap 247 is pivoted at the point 250 to a latch 30 lever 251, which in turn is pivoted at 252 to outwardly extending lugs 253, carried by the wall 247 of the vacuum chamber L. As clearly shown, the movement of the levers 251 into locking position causes the straps 247 to be moved beyond 35 dead center and in this way the straps are locked and the tank J is securely clamped to the structure below it.

Since the chamber L is to contain air at subnormal pressure it is necessary to provide an air-tight joint at the upper end of the peripheral wall 246. This is accomplished by using a band or belt 254 of rubber or like resilient material which when slipped into place over the upper edge of the wall 246 and the adjacent portion of the 40 upper tank wall 241 will be under tension and thereby firmly pressed against the tank wall. Thus, it will keep itself in tight contact with the engaged parts and thereby maintain a tight joint, with a resulting good vacuum. In order to help 45 position the strap 254, the wall 246 is provided with a bead or outward projection 257 which is preferably formed by suitably shaping the metal throughout its periphery a little below the upper edge of the wall 246.

55 In addition to these parts, there is a leak tube 255 secured to the bottom 168 of the tank J in such a way as to bring the vacuum tank L and the trap tank G into communication with each other. The opening through the tube 255 is not 60 large but will allow for equalization of pressure in the two tanks, which equalization is desirable under certain conditions of service.

The receptacles M are shown as glass milk 65 bottles but, as previously indicated, glass bottles may give way to receptacles of other form, material and construction. The term bottles is used, however, in a broad sense to cover such receptacles both in the specification and in the claims.

The piping N for bringing milk or other liquid 70 to the dump tank J may take many different forms. In the present instance a horizontal pipe 257 is placed in communication with the vertical pipe 258 which is telescoped into a vertical pipe 259 carried by the tank J. A suitable valve 260 is 75

associated with pipe connections 261, at the point where the pipes 257 and 258 are in communication, to control the flow of milk or other liquid into the tank. The pipe 259 is flanged at its upper end and by its flange is held up against its seat 262 by a clamping nut 263. The ring 262 is positioned in an opening in the center of the top 240 of the tank J. It will be seen that by loosening up the nut 263 the pipes 258 and its 10 connections, as well as the pipe 259 may be readily removed for cleaning.

At the lower end of the pipe 259 is a valve 264. This is part of the float valve mechanism O. A float 265 acting through an arm 266 controls the 15 movements of the valve 264 according to the level 267 of the milk or other liquid in the dump tank. The valve mechanism O is preferably the same as that disclosed in A. B. Mojonnier's prior Patent No. 1,956,077, granted April 24, 1934, and 20 need not be further described.

Coming now to the valve mechanism P, wherein we have the inlet valve 204 and the outlet valve 205, we find mechanism which is operated in response to variations of applied air pressure. 25 The air is applied to a bellows 270, shown more particularly in Fig. 5. The path by which the compressed air comes from the left hand portion of groove 80 of the stator (see Fig. 8) to the bellows by way of the flexible tube 146 has been 30 previously traced. This path, as traced, brought us to the nipple 153, which is connected to the bracket 271, of the mechanism P. This bracket, as clearly shown, is connected to the under wall 226 of the vacuum chamber L. The connection 35 is preferably made by passing bolts 272 through a flange 273 on the bracket and providing the threaded ends of the bolts with cap nuts 274. The bracket has a specially shaped pedestal or base portion 275 upon which the bellows 270 is mounted.

The bellows 270 includes a base member 276 which fits over a sleeve 277 formed upon the pedestal 275. A gasket 269 lies between shoulders on the member 275 and 276. A bolt 279 passes through a central opening in the pedestal 275 into threaded engagement with a threaded central opening in the member 276. A pin 282 keeps the members 275 and 276 in alignment, the pin passing into suitable bores in each of these members and preferably fixed in one of them. 45 Washers 283 lie between the head of the bolt 279 and an adjacent shoulder upon the base 275. The forward end of the base 276 forms an adjustable abutment for the movable bellows head 284. The 50 head 284 has a threaded shank which passes through an end member 285 and the end 286 of a casing. Nuts 287 and 288 are threaded onto the stem of the head 284 and firmly hold it and the casing together. The casing 286 includes a 55 circular end and a skirt 289 which incloses the expandable member 290 of the bellows and travels freely at one end over the outside of the base 276. A sleeve 291 is secured at one end to the base 276 and at its other end has an inturned flange 292 60 which cooperates with a flange 293 on the member 284 to limit the movement of the latter under the expanding action of the mechanism. The member 290 is made up of convolutions or flutes and is secured at its opposite ends, one end to the 65 base 276 and the other end to the head 285. Air is admitted to the interior of the chamber, and when it is air under pressure, the bellows head is forced inward, that is to say, toward the center of the trap tank G, and then, following, when normal pressure returns, the member 70

290 contracts and the bellows head recedes. This receding of the bellows head is assured by reason of a spring 311 associated with the actuating member 295 which cooperates with the bellows 270. The head of the bellows is provided with a 5 threaded pin 294 which coacts with a head 310 on the member 295. This pin 294 is threaded into the bellows head and is therefore adjustable to vary the point in the inward movement of the bellows at which the head 310 will be contacted 10 and the movement of the member 295 will be started.

The air passages from the supply pipe 153, previously mentioned, include passages 296, 297, 298 and 299. The openings made by drilling these 15 passages are closed by plug screws 300, 301.

From what has been said, it will be seen that while the carrier C is traveling through approximately a half revolution, air under pressure will be supplied to the bellows 270, and, while the 20 same is passing through the remainder of its revolution, air at atmospheric pressure will be supplied to the bellows. This means that during one-half of the rotation, the bellows will have its head 284 and actuating pin 294 projected and 25 during the balance of the rotation these parts will be in a withdrawn position.

The member 295 which is actuated by the bellows 270 carries a yoke 305 at its inner end. This yoke operates to actuate the weighted levers 306 and 307 of the inlet and outlet valves 204 and 205, respectively. The member 295 is in the form of a tube which is mounted for reciprocation in a sleeve 308 supported at its outer end within a tubular bearing 309 formed in the wall 198 of the 30 trap tank G. The outer end of the sleeve 308, 35 namely, that adjacent to the tubular bearing 309, is reduced in diameter to provide a shoulder which abuts against the inner end of the bearing 309. A nut 304 is threaded upon the outer end of the 40 sleeve 308 and when screwed home bears against the outer end of the bearing 309 and thus holds the sleeve 308 firmly in place. The yoke 305 is threaded upon the inner end of the tubular member 295. It will be noted, too, that the yoke 305 is held against rotation in the sleeve 308 but is 45 free to reciprocate therein through a limited distance. This is brought about by providing a slot 330 in the tube 308 and a cooperating finger or feather 331 upon the yoke 305. In this way the 50 tappet ends of the yoke are in proper position at all times for engagement with the cooperating members of the inlet and outlet valves 204 and 205. At the outer end of the member 295 is a 55 headed screw 310 which is threaded into the open end of the tubular member 295. The coiled compression spring 311 bears at one end against the head of the screw 310 and at the other end against the outer end of the sleeve 308 or the nut 304 mounted upon it. The action of the 60 spring 311 is to force the member 295 outward. Its outward movement may in some instances be limited by the yoke 305 engaging the inner end of the sleeve 308 but preferably this outward movement is limited by the head of screw 310 engaging 65 screw 294 in the bellows head 284 and the shank of this head engaging the end of the pedestal member 276. The inward movement of the member 295 is preferably limited by the inward stroke of the bellows, although it is obvious that the 70 contacting of the turns of the spring 311 upon each other would accomplish the same result should this occur before the bellows reached the end of its stroke.

The tubular member 295 is provided with sev- 75

eral slots 312. These are located just inward of the screw 310 and in position to establish communication between the interior of the tube 295 and the space surrounding the outer wall 198 of the trap tank G. In other words, when the member 295 is in its outermost position, communication is established between the interior of the trap tank G and the interior of the main tank E. It will be noted that the sleeve 308 has a tight fit in the bearing 309 and hence there can be no communication between the two tanks mentioned except it be through the interior of the member 295 and the slots 312. It will also be observed that when the member 295 is in its innermost position, the slots 312 are covered by the outer end of the sleeve 308 and hence such communicating passage between the two tanks is closed. The outer end of the tubular member 295 with its headed screw 310 projects through an opening 313 in the wall 158 of the tank E. This is the only opening between the interior of this tank and atmosphere when the machine is operating. It will be noted that it is well above the milk level 180 in the tank.

Considering the inlet valve 204 and its mounting, shown more particularly in Figs. 4 and 13, it will be noted that the lever 306 is pivoted to oscillate upon a support 315. This support is stirrup shaped and its reduced ends pass through apertures in the wall 198 of the trap tank G and the whole is held in place by nuts 316 screwed home upon the stirrup ends against the outer face of the wall 198. A similar support 317 is provided for the lever 307 of the outlet valve 205. And, again, a similar member 318 is provided at the opposite side of the tank G and here it serves as a handle for grasping the tank when removing it from the main tank E. The levers 306 and 307 constitute hinge members upon which the valves 204 and 205 are mounted respectively.

It may be noted at this point that in the several figures where the valves 204 and 205 are shown, they are in a neutral position, both being closed. In the operation of these valves, this position is but momentary and exists only when the valves are shifting between the more usual positions wherein one is open and the other closed.

The flap valves 204 and 205 are similar in construction. Referring to the valve 204, it will be seen that it comprises a disk-like body having a stem 319 at the outer end of which is a bead 320. The adjacent arm of the lever 306 is provided with a bore for the reception of the stem 319 and this bore is provided with a circumferential groove on its inner wall so as to form a small annular recess or seat for the bead 320 upon the stem. With this construction, the valve 204, which is composed of suitable resilient material, may be readily slipped into place or withdrawn therefrom for cleaning. The valve 205 is the same in construction, and although the bore in the depending arm of the lever 307 is somewhat longer yet it is similarly provided with a groove or recess for a bead upon the valve stem. In the case of the previously described disk valve 193, located at the lower end of the feed pipe 188, there is the same structure and the valve cooperates with its support in the same way. All these valves are capable of ready removal for cleaning purposes. They are preferably composed of a rubber compound suited to the purpose.

In the case of the lever 306, the inner arm of the lever is provided with a weight 321 which, when unrestrained serves to move the inlet valve 204 toward its seat 206. The valve lever 307 is pro-

vided with a weighted portion 322 which serves a like purpose with respect to the outlet valve 205. In other words, the weighted portion 322, being situated as it is, tends to draw the valve 205 against its seat 323. Both bearing members 315 and 317 are provided at their centers with reduced pivot portions 324 and 325, respectively. These portions engage circular openings in the respective valve levers. These openings are provided with slots 280 and 281, respectively, and the adjacent bearing portions 324 and 325, which form the pivots for the levers, are flattened on opposite sides so as to give a dimension which will allow the lever 306 to be disconnected from its support when moved to a disengaging position. In both cases this will be found by moving the free portion of each lever inward and upward until the walls of the respective slots 280 and 281 lie in horizontal register with the flattened portions of the pivots 324 and 325. When in this position in each case, the valve lever can be readily removed from, or placed upon, the stirrup bearing.

It will be noted that in the case of the inlet valve 204, the yoke 305 has an end 327 which is adapted to engage behind projection 328 upon the lever 306. This means that when the yoke moves inward toward the center of the pan G, it will apply force tending to withdraw the valve 204 from its seat.

In contrast to this the other end of the yoke, viz., the end 328, lies inward of a projection 329 upon the valve 307 and in line with it so that when the yoke moves outward away from the pan center, it will act upon the lever 307 in a direction to apply force tending to unseat the outlet valve 205.

As these valves are brought into action to place the intervening trap tank G first in communication with the vacuum chamber L and then into communication with the main tank E, they will operate in the following way. If we assume that the outlet valve 205 is open and that the inlet valve 204 is closed, as would be the case when the bellows 270 is supplied with air at atmospheric pressure, then it will be seen that the tanks G and E will be in communication and the pressure of the air within both will be that of atmosphere. At such time, any milk that may have been transferred to the trap tank G, will pass through the opening controlled by the valve 205 and be deposited in the main tank E. At this time there will be some flow of air from the tank G through the equalizing pipe 255 into the vacuum chamber L but the flow will not be large enough to materially modify the low pressure of the vacuum. While the parts are still in this position, it will be observed also that air may pass through the tube 295 between the tanks G and E. This action, of course, will produce no result since the pressure at both ends of the tube is the same. The passage through tube 255 is of leak size. Thus there is always a leak between chamber L and tank G. An equalizing tendency between the pressures in the two chambers is the result.

Now, assuming that compressed air is supplied to the bellows 270, and that it is actuated to move the yoke 305 inward toward the pan center, then the movement of the member 295 will at once cut off the passage through its interior by closing the slits 312 as before pointed out. The inward movement of the yoke 305 will not affect the outlet valve 205 because the end 328 will move away from the projection 329 upon the lever 307. In other words, the yoke 305 normally keeps the outlet

valve 205 open but when the yoke moves inward it does not positively close the valve 205 but leaves it free to act under the influence of its weight 322 and other forces. The action of the weight 322 tends to bring the valve 205 into closed position upon its seat 323. Then any reduction in air pressure within the tank G over that in the tank E will tend to clamp the disk valve 205 tight against its seat.

On the other hand, the inward movement of the yoke 305 will positively draw the lever 306 inward against the force of its weight 321 and will open the inlet valve 204. When this occurs, there will be a reduction of the air pressure within the tank 15 G by reason of its direct connection with the vacuum chamber L. As soon as the outlet valve 205 is closed there will be a certain amount of air flow through the equalizing or leak pipe 255 between the chamber L and the trap tank G. In 20 this way a by-pass for the flow of air from one chamber to the other is provided around the passage controlled by the inlet valve 204. It should be noted that the action of the equalizing pipe 255 will lower the pressure in the trap tank G even 25 before inlet valve 204 is opened and this lower pressure facilitates the closing of outlet valve 205 as noted. Hence, there will be less interference with the liquid which passes from the vacuum chamber L into the trap tank G. If all of the air 30 had to pass through the opening of the inlet valve 204 then there would be more disturbance than is desirable with milk, cream and other milk products. The by-passing of the air in this way is therefore quite important.

As before stated, when the air within the trap tank G is lowered to that of the air in the vacuum chamber L then the outlet valve 205 is more firmly seated. Therefore all the milk or other liquid which passes from chamber L into trap tank G is held in the latter until the carrier of the filler has traveled far enough to bring its supply port 142 beyond that portion of the outer groove 80 of the stator which is supplied with compressed air. This means that the bellows 40 270 is at this juncture connected to atmosphere. As soon as this takes place, the bellows returns to normal and the actuating member 295 moves to its outer position. In this position, as before noted, the interior of the tank G is connected 45 through the slots 312 to the interior of the tank E. This means that air at atmospheric pressure will rush from the latter into the former to equalize the pressures in the two tanks. The inward movement of the yoke 305 will bring a direct application of force to the lever at 307 and force 50 the outlet valve 205 open. This will occur only after there has been some approach to equalizing the pressure in the two tanks. Consequently the milk or other liquid which has been collected in 55 the trap tank G will pass through the opening of valve 205 into the main tank E. Of course, when the latter valve is fully open, the pressures within the two tanks G and E becomes equal and is that of atmosphere. The outward movement of the 60 yoke 305, which caused this positive operation of the outlet valve 205, merely frees the inlet valve 204 for action. As soon as pressure within the tank G begins to increase, the effect of the same will be to quickly close the valve 204 upon its 65 seat. This time there will not be enough flow of air through the equalizing pipe 255 to interfere with this action. While the parts are in this position, milk will accumulate in the chamber L, or, rather, in the chamber just outward of the 70 inlet valve 204, and perhaps reaching up into 75

the chamber L also, and this action will continue until the rotor has again made a half revolution, so as to bring the compressed air again into play. As soon as this point is reached, there has been one complete cycle of operations.

From what has been said, it will be seen that the trap tank serves as an air lock to pass liquid drawn into the vacuum chamber back into the main tank. The small chamber formed within the wall 215 about the inlet valve 204 is a sort of 10 vestibule between the vacuum chamber L and the trap tank G. Since the action of the valves 204 and 205 is produced by the rotation of the carrier, there is then one complete cycle of valve operations for each rotor rotation.

From the description thus far given, it will be seen that the various elements of the filler may be readily separated for cleaning purposes, as is so necessary where milk or milk products are being filled into the receptacles. Thus, beginning 15 at the top of the machine, the pipe 257 may be readily disconnected from the valve 260 by removing the appropriate connecting gland 261. Similarly the pipe 258 and valve 260 may be disconnected by removing the lowermost gland 261. Then the pipe 258 may be withdrawn from pipe 259. When these parts have been removed, then the nut 263 may be turned off and the pipe 259 withdrawn from the valve 264. The various parts which constitute the structure of the valve 30 mechanism O may also be separated in the manner pointed out in U.S. Patent No. 1,956,077, previously mentioned. The valve mechanism O may be taken from the dump tank by withdrawing it through one of the openings 242. All these parts 3 when once removed are capable of being readily separated and cleaned.

Having withdrawn the supply piping N and its associated valve mechanism O from the tank J, the main elements of the machine may be separated for cleaning as indicated by the diagrammatic view of Fig. 15. Obviously, the separations and cleanings may take place in different orders. But for the purposes of this disclosure one order will be followed.

With the piping N and valve mechanism O removed, tank J may be readily cleaned. This may be done by reaching through one of the openings 4 242. As soon as the locking straps 247, which hold the dump tank J in place, are moved to releasing position, then the rubber band 254 may be removed from its seating position. Likewise the dump tank J may be lifted and separated from the other parts. This also means that the feed pipe 188 connected to the under side of the bottom 168 of the dump tank may be removed from the latter. This may be done by simply drawing the two apart.

When the dump tank J is removed, then the ring K may be removed. When this is done the trap tank G, and the associated valve actuating mechanism, which is carried by it, may be lifted from the main tank E. The bellows outside the main tank is entirely incased and does not require special cleaning. When the trap tank G is lifted out of the main tank E, the float tank F and its valve may be lifted out with it. This is due to the fact that the tank F may have such frictional engagement with the feed pipe 188 that it will be necessary to lift both tanks G and F out of the main tank E before separating them, as may be desirable for cleaning purposes. The valve mechanism P, within the tank G, may be taken apart as will be apparent from the previous description. The valves 204 and 205 may be

withdrawn from their actuating levers and those levers may be lifted from their supports. Likewise the yoke 305 may be removed and the tubular member 295 which carries the yoke withdrawn and all of the parts thoroughly cleaned.

When the tanks F and G are removed from the main tank E, then the interior of the latter may be thoroughly cleaned also. If desired the main tank E may be lifted together with its supporting bowl, from the carrier C below. This may not always be desirable but can be done if deemed best. The remaining parts of the rotor need not be especially cleaned and therefore may be left without removal from the stator and all of these can be given their customary cleaning when the parts are thus separated. The cleaning referred to is that thorough cleaning which is necessary where milk and milk products are being handled. It usually calls for a scrubbing of the various parts with which the milk comes into, or may come into, contact.

Calling attention now to the capper Q, it will be seen that the same includes a tubular standard 333, a carrier 334 mounted to rotate about said standard, suitable bottle supports spaced around the periphery of the carrier, a supporting head 335 located at the upper end of the standard, capper heads 336 carried by the supporting head, a cam 337 at the upper end of the standard, and operating mechanism 338 by which the requisite movements are brought about in applying the caps. As before stated, the capper forms no part of the present invention. Its principal elements are merely mentioned without according them specific description.

Suitable conveying mechanism T is employed to carry the bottles along. They are first presented to the filler, then conveyed from the filler to the capper, and then from the capper to a suitable delivery point. The parts which cooperate in producing this travel, include notched conveyer wheels 337, 338 and 339 and a guide member 340. The wheels are mounted on vertical shafts which are journaled in the machine frame and the member 340 is suitably supported by short posts 341 which extend upward from a table 346. The table 346 is carried by the casings 347 in which the notched wheel shafts are journaled, as will be clear from an inspection of Fig. 1. The member 340 cooperates with the notched wheels in providing three distinct bottle passages. One of these is the passage 342 which leads from the incoming portion of the conveyer 343 on to the filling machine lifters D. The second is the passage 344 leading from the filling machine lifters D to the rotor of the capper Q. And the third is the passage 345 leading from the capper to the delivery portion of the conveyer 343. The direction of travel is indicated by the several arrows in Fig. 6 where these parts are most clearly shown.

In order to adjust the filling and capping machines as a unit, for the purpose of suiting the same to bottles of different sizes, the adjusting mechanism W is employed. This mechanism is substantially the same as that disclosed in our aforesaid Patent No. 1,966,889. It includes a heavy rock-shaft 349 which is journaled in suitable bearings formed in brackets 350 and 351 secured to the under side of the base A. This rock shaft is provided with upwardly extending crank arm 352 which is suitably secured to the shaft. The upper end of the crank arm 352 is pivotally connected to one end of a horizontally disposed member 353. The opposite end of this member is provided with a threaded opening through which

extends a screw 354. This screw is connected by suitable means to a crank 355 journaled in bearing members 348 provided in the base A. It will be seen that as the crank 355 is turned, the member 353 will be moved to and fro along the screw 5 and in consequence thereof the rock-shaft 349 will be given a rocking movement. Because of the screw connection the rotary adjustment of the rock-shaft can be accomplished with great accuracy and nicety. As the shaft is rocked, the 10 filling and capping machines are raised and lowered through the agency of rock arms 356 and 357, respectively. These arms are fixed to the shaft 349 and extend in bifurcated ends on opposite ends of the axes of the two machines, respectively. 15

Since the capping machine in itself forms no part of the present invention, it will not be necessary to describe the connections of the various capping machine parts to the actuating arm 357. 20 For details concerning the capper, reference should be had to our aforesaid Patent No. 1,966,889 or to our aforesaid copending application.

Referring, however, to the crank arm 356, which has to do with the filling machine, it will be noted that its bifurcated arms 358 pass upon opposite sides of the thrust bearing B' located at the bottom of the central column B of the machine. Links 359 cooperate with the bifurcated ends 358 30 and are pivotally connected to the lower portion of the bearing B' by suitable pivot pins 360. It will be obvious that when the adjusting shaft 349 is rocked the crank arm 356 will act through the links 359 to raise and lower the thrust bearing B' 35 to bring about vertical adjustments of the central column of the filling machine, which will be held in place by the catch mechanism B², as previously explained. Of course, since the capper is provided with a similar connection through the crank 40 arm 357, it necessarily follows that vertical adjustments of the filling machine will be accompanied by similar adjustments of the capping machine just as in our aforesaid Patent No. 1,966,889. Thus, an adjustment which suits the 45 filling machine to a given size of bottles will also suit the capping machine to the same.

At this point, the thrust bearing B' may be considered a little more fully. The details of this bearing are shown particularly in Fig. 22. Upon examination it will be seen that the tube 51 of the central column B is provided at its lower end with a bearing sleeve 361 which is inwardly flanged at its lower end and rests upon a thrust ring 362 carried upon the bottom 363 of the body 364 of the bearing. It is this portion 363 into which the pivot pins 360 extend. The thrust ring 362 is held in place by suitable pins 365 which also enter the bottom 363. The upper end of the bearing sleeve 361 is similarly engaged by a thrust ring 366 held in place by pins 367 which enter openings in a cover plate 368 which in turn is held in place by screws 369 which enter the outer portion of the body 364 of the bearing. 55

For the purpose of driving the various parts of the filling and capping machines in proper timed relation, suitable gearing must be provided. This gearing is also similar in arrangement to that disclosed in our aforesaid Patent No. 1,966,889. In the present instance, power for driving the 70 rotor of the filling machine is furnished by the electric motor X. This motor drives a main shaft 373 by a belt 374 which passes over a pulley 375 mounted upon the shaft 373. The belt 374 and associated pulleys 375 and 376, the latter being 75

on the motor shaft, are preferably inclosed in a casing 377 for safety. The shaft 373 is suitably journaled in bearings upon the base A. The armature shaft of motor X is also provided with a 5 crank 370 so that when the machine is not being driven by the motor the main shaft may be turned by hand to bring the different parts of the machine to desired positions.

The inner end of the shaft 373 carries a bevel 10 pinion 378. This pinion engages a large bevel gear wheel 379 keyed to a vertical shaft 380 which is suitably journaled in the floor 30 of the base A. The shaft 380 also carries a pinion 381 which is firmly keyed to it. The pinion 381 engages a 15 gear wheel 382 which is keyed to a vertical shaft 383 also mounted in the floor 30 of the base. The gear wheel 382 engages the gear rack 105 of the carrier C and through this train of gearing the latter is rotated. The shaft 383 also carries the 20 notched conveyer wheel 338 which serves to convey bottles from the filling machine to the capping machine. At the time the rotor is traveling its toothed rack 105 engages the teeth of a gear wheel 384 keyed to the shaft 385 and lying in the plane 25 of the rack 105 and rotates the same. The shaft 385 is also suitably journaled in portions of the main frame and has the notched conveyer wheel 337 secured to its upper end. The notched wheel 339 is mounted upon the upper end of a shaft 386 30 which is also journaled in the frame A and is driven through the agency of suitable gearing (not shown) operating in conjunction with the gear wheels just described.

Thus, all the movable elements of the filling 35 machine and all the rotary elements of the conveyer are driven from the main shaft 373. The various conveyer parts need not be described. Obviously, any one of a number of available conveyers will do the work and may be used.

40 It will be remembered that as each lifter passes over the segment of the stator grooves 80 and 81 lying between plugs 84 and 85, it will receive a charge of mingled air and oil. This injection into the interior of the lifter is made for lubricating purposes. As previously stated, the air 45 for this purpose is supplied through the pipe 90. The atomizing device which we use is illustrated more particularly in Fig. 25. The same includes a body 390 in which a Venturi tube member 391 is located. The pipe 90, which brings in the compressed air, is connected by a coupling 392 into a threaded opening formed in one side of the body 390. A channel 393 continues the air passage to an interior chamber 394. The point of the Venturi tube extends through this chamber and 50 terminates at the upper side of an opening 395 in a transverse wall 396. The mixing chamber 397 lies above the wall 396. The oil is supplied through the axial passage 388 in the Venturi tube member 391. As the oil presents itself at the top 55 of the tube, the air under pressure, flowing through the aperture 395, takes up oil, and a mixture of oil and air is the result. The two elements are thoroughly mixed in the chamber 397 and pass upward through the pipe 398 (shown 60 also in Fig. 11) into the opening 88 in the oiling section of the stator. The oil furnished to the device is supplied through a pipe 399 which is threaded into a suitable opening in a plug 400 located at the bottom of the body 390. As the 65 parts are shown in Fig. 25 the plug terminates at the line 401 and there engages the bottom of the Venturi member 391. The latter is threaded into a reduced portion of the bore of the member 390 as indicated at the point 402. The central 70

passage 393 in the Venturi member registers with the opening 403 in the bottom cap 400. In practice, the oil is passed into the oiling device under a slight pressure. Just enough oil is ordinarily passed to meet the needs. However, if there be a slight surplus the latter drains through passages 404 and 405 into the chamber 406 around the Venturi member. From the chamber 406 it may be withdrawn, or returned to the oil supply if desired.

10 As shown in Fig. 8, the pipes 90 and 91 which furnish air under pressure to the air ports 88 and 89 are preferably terminal branches from the line pipe 407 which extends to the control board 408 at the front of the machine. This board is 15 secured to the base A and carries a valve 409, shown diagrammatically in Fig. 8. The valve 409 has an outer casing 410 and an inner rotary valve member 411. When the valve is in open position, a passage 412 in the member 411 connects the pipes 413 and 407. Obviously, when in cutoff position, the member 411 cuts off the communication between these pipes by closing one or both of the pipe ports in the casing 410. A handle 414 controls the valve 409. Obviously, 20 the pipe and valve connections may be varied. It is important, however, that the stator ports 88 and 89 be connected to a compressed air supply line whenever the machine is in readiness for operation. A suitable opening 387 in the vertical wall 32 of the frame A permits the passage of the pipe 407 which is preferably copper tubing capable of being readily bent about when shaping the same for installation.

25 In addition to furnishing air to the stator ports, 35 as just pointed out, it is quite important to operate other parts by air from this same source. Accordingly, the pipe 91 which furnishes air to the port 89 is in direct communication with the pipe 389, as clearly shown in the piping diagram 40 of Fig. 26. The pipe 389 communicates with a passage 415 in a manifold 416. From the passage 415 a tubular jumper 417 communicates with a passage 418 in the manifold. From the passage 418 a pipe 419 leads to an opening 420 in the 45 push button body 421. This body is also provided with a port 422 which is in direct connection with a pipe 423 which returns to a more or less common opening 424 in the manifold 416. The valve body 421 is also provided with an outlet 425 which leads to atmosphere. A plunger 426 is located within the push button body 421. These two parts, the plunger and body, constitute a piston valve. When the push button parts are in the position illustrated in Fig. 26, then, obviously, the chamber 424 of the manifold 416 is connected to atmosphere. Again, when the plunger 426 is moved upward into the dotted line position of Fig. 26, then the plunger will connect ports 420 and 422 and thereby put the chamber 424 of the manifold into direct communication with the compressed air supply. The plunger 426 is provided with a reduced portion 427 which forms the uniting passage between the different valve ports as the push button is moved downward and upward. As clearly shown, the upper end of the plunger 426 is provided with a cap 428 which is secured in place by a screw 429. The cap 428 has a skirt which passes down over a tube 430, secured to the top of a box 431, mounted upon the top of a tubular pedestal 432, which at its lower end is suitably carried by the frame of the machine. The end of the bore or chamber 424 in the manifold 416 is suitably closed by a screw 433. Openings 434 are provided in the body of the 7

manifold to enable the same to be secured by screws to any desired part of the machine frame A or other support.

From what has been said, it will be seen that the "down" position of the plunger 426 supplies the manifold chamber 424 with air at atmospheric pressure and the "up" position supplies the same chamber with compressed air. Two mechanisms are operated by compressed air taken from this manifold chamber. One of these is a butterfly valve 435 located in the vacuum supply passage adjacent to the exhaust pump Z. The other mechanism operated by compressed air from the same manifold chamber, is an electric switch 436, mounted in a switch box 437, carried by the casing 377 of the electric motor X. In both cases, air under pressure operates a bellows and the bellows actuates the valve or switch as the case may be. In the case of the butterfly valve 435, a pipe 438 leads from the chamber 424 to the bellows 439. On the other hand, in the case of the motor switch, a pipe 440 leads from the manifold chamber 424 to a leak valve 441. From the valve 441 the passage is continued through a pipe 442 to the bellows 443. In the case of the leak valve 441 a lower member 444 provides a seat 445 at its upper end. This seat is provided with a groove or by-pass 446. When the ball valve 447 is on the seat then a small amount of air will pass through the groove 446. The valve is held more or less firmly upon its seat by a coiled compression spring 448 which acts between the ball and the end of the cap 449 into which the pipe 440 is threaded. It will be seen that when air is admitted to the manifold chamber 424, it will be supplied promptly to the bellows 439 and less promptly to the bellows 443. This will mean that the butterfly valve 445 will be operated in advance of the switch 436 whenever the push button is moved to its upper position. Of course, when the manifold chamber 424 is connected to atmosphere then the air will exhaust through both pipes at about the same rate. During the exhaust the ball 447 will be pushed upward against its spring 448 as will be obvious and the outflow of air will be more rapid than the retarded inflow.

The bellows 439 and 443 are identical in construction. It will therefore suffice to describe the bellows 443 which has its parts illustrated in central section. As shown, there is a base 450 secured to an adjacent wall of the switch casing 437 by one or more screws 451. Secured to this base is a sleeve 452 which has an in-turned flange 453 at its distant end. Just beyond the flange 453 is an end member 454 which is threaded upon a central core 455. The expansible member of the bellows is a corrugated or fluted tube 456 which is secured at one end to a rim 457 upon the base and at its other end to the periphery of the end member 454. The core 455 has threaded into it a bolt 458 which is pivotally connected at its outer end to a switch actuating member 459. The core 455 has a central chamber 460 which is formed by boring out that end of the member. At the base end of the member 455 is an outwardly extending flange 461. Between the flange 461 on the member 455 and the flange 453 on the sleeve 452 is a coiled compression spring 462. Within the base 450 is a passage 463 which places the interior of the pipe 442 into communication with the space between the sleeve 452 and the communicating tube 456. In addition to obtaining access to this space just within the corrugated tube, the sleeve 452 is provided with openings 464 on op-

posite sides, and likewise the tubular wall of the member 455 is provided with openings 465. Thus, it will be seen that when compressed air enters within the bellows, it pushes the core member 455 outward against the action of the spring 462. The outward movement of the core 455 is limited by flange 453 engaging an annular shoulder 466 upon the core. Such action of the bellows will throw the switch member 459 to the right as the parts are shown in Fig. 26. This action will, however, be slowed up on account of the building up of pressure only through a supply of air which must pass through the ball valve leak passage 446. Obviously when the bellows is placed in direct connection with atmosphere, the spring 462 will move the parts back to the position illustrated, and this will bring the switch arm 459 back to its normal or open position.

In this connection, it may be stated that the position of the switch actuating member 459, as shown in Fig. 26, is open. When said member 459 is moved to the right, as the parts are shown in said figure, then the motor circuit is closed and the motor starts operating. The particular electric switch which has been used in the operations of machines constructed in accordance with the invention, is a standard Allen-Bradley manually operated switch No. 609 of well known construction, and for that reason it is believed that the same need not be further described. On the under side of the switch box 437 and leading from it to the interior of the motor casing is a tubular conduit 484, through which suitable interconnecting wires pass. The wires 485 which enter the under side of the box 437 are supply wires leading from supply mains to the interior of the switch box 437. Here they connect with terminals of the electric switch 436 and the latter in turn is properly electrically connected with the motor windings through the conduit 484.

Turning now to the bellows 439 which operates the butterfly valve 435, it will be seen that air under pressure coming through the pipe 438 to the bellows will move the same to its open position, whereas the supply of air under atmospheric pressure will cause the bellows to return the butterfly valve to its closed position. In this case, the bellows base is secured by screws 466 to an adjacent wall of the butterfly valve casing 467. The front 468 of this casing is removable so that the bellows and its connections may be inspected or replaced as may be required. It may be noted that the closed position of the butterfly valve 435 is shown in Fig. 26. This closed position is not one in which the plane of the valve is at right angles to the axis of the opening 469 in which it is located. Instead, the plane of the valve is approximately 45 degrees from such transverse plane. When the valve 435 is in this closed position, there will be a certain amount of suction by reason of the small opening 470 which extends completely through the valve blade. As clearly shown in Fig. 26, the end of the tubular portion of the casing 467 is firmly secured to an armored tube 471 which leads from the casing 467 of the butterfly valve, to the casing of the thrust member B', shown more particularly in Fig. 3. The casing 467 is suitably secured to the lower flange 31 of the base A. The face 472 of the casing 467 abuts against the casing 473 of the pump Z and a tight fit is established by any suitable means. The pump Z is preferably of blower construction and is driven by the electric motor Y through the agency of a belt 474, engaging pulleys 475 and 75

476 upon the shafts of the motor Y and the pump Z, respectively.

The butterfly valve 435 is carried upon a shaft 486 which is suitably journaled in a bearing 487 positioned in an adjacent bore extending through one wall of the casing 467. At its outer end the shaft 486 carries a crank 488, to which a bearing member 489 on the movable head of the bellows 439 is located. As the bellows head moves to 10 and fro, the butterfly valve is rocked back and forth between its open and closed positions.

The plate 408 at the front of the frame A besides carrying the valve 409, carries a pressure gauge 477 which indicates the pressure in the 15 compressed air supply pipe 407. Besides these there are in the full filler and capper installation, valves 478 and 479 associated with corresponding gauges 480 and 481, respectively. These latter valves and gauges have to do with the 20 capper Q and its operation and need not be described further. Besides the valve 409 in the compressed air supply, there is also preferably another cut-off valve 482 which is interposed between pipe 483 and pipe 413.

In the operation of the machine the main 25 tank E is filled with milk to a point permitted by the float tank F, then the motor Y is started and the pump Z proceeds to exhaust air from the machine. At this time the butterfly valve 30 435 is in closed position, and the vacuum produced by the operation of the pump is the partial vacuum, which results from the suction of air through the small opening 470 in the butterfly valve. The low vacuum thus produced in the 35 connecting passages and in the vacuum chamber L, will not be sufficient to cause milk to flow upward through the milk pipes 178 into the heads H. This would be true even though in any instance a bottle was up against the cushion 229 of its head H and thus provided a tight seal. 40 Ordinarily, however, at this time there will be no bottles upon the lifters D and the partial vacuum will produce no beneficial result. Having started the vacuum pump Z, the next step is to 45 press the push button plunger 426 upward so as to actuate the motor starting switch 436 and the butterfly valve 435. By reason of the retarding effect of the leak valve 431, as before pointed out, the butterfly valve 435 will open before the motor X can start the rotor of the 50 machine. The full vacuum resulting from the opening of valve 435 will have no different effect at this time, insofar as filling bottles is concerned, than would the low vacuum. This is 55 true for the reason that at this time, under the assumption, there are no bottles on the lifters of the machine. Obviously, after the motor X is started and the machine rotor begins its rotations there will be the usual up and down traverse of the bottle lifters. This follows because 60 of the supply of compressed air to them through the stator ports 88 and 89. The lifters will rise as they individually pass plug 84 and will remain elevated until they pass plug 86 whereupon they will fall and remain in fallen position until 65 they again pass plug 84.

Still there will be no lifting of the milk from the 70 main chamber E because of the absence of bottles or other containers to complete the path for the flow of milk. But as soon as bottles are placed upon the lifters they will be raised successively into engagement with their filling heads, and at once, for each individual bottle as it presents itself, the vacuum path will be established 75 by the bottle engaging its cushioned filler head

and the full vacuum will be applied. The vacuum pull, so to speak, will be sufficient to cause a flow of milk up into the bottle and on into the vacuum chamber L. As soon as the bottle under consideration, now having been filled, is lowered 5 away from its head so as to break the vacuum in the path by which it was filled, then the bottle will be skimmed of its froth, foam and surplus milk. This will have occurred in any given case as soon as the lifter upon which the bottle 10 is located, passes over the plug 86. Then it is that the air beneath that particular bottle is exhausted to atmosphere.

It will be noted that the bottles are continued in contact with their heads a sufficient length of 15 time to permit all the foam and some of the milk to pass up into the vacuum chamber L. Because of the low point on each head H being the substantially horizontal face 222 in which the port 20 221 of the vacuum passage 227 is located, it follows that there will be a clean leveling of the milk to the plane of the face 222 and a clean bottle top left.

After considerable milk has been brought into the vacuum chamber L, then it must be locked 25 back into the main tank E. This is brought about through the action of the valve mechanism P and the trap tank G. As before pointed out, during approximately a half revolution, the inlet valve 204 is open and outlet valve 205 is closed. 30 During the remainder of the revolution, the reverse valve condition exists, viz., valve 204 is closed and valve 205 is open. As before explained, when inlet valve 204 is open and outlet valve 205 is closed, all the milk which has accumulated in 35 the vacuum chamber L and adjacent vestibule, will flow down into the trap tank G and be held there for subsequent release. Then, when the valves change their positions, and inlet valve 204 is closed and outlet valve 205 is open, then no 40 milk will pass from chamber L to tank G, but, on the other hand, all milk in tank G will pass at once into tank E.

From what has been said heretofore, it would seem that the butterfly valve 435 performs no 45 particular function. But there is a condition in which it is useful. If, while the machine is operating normally, filling bottles in regular course, it becomes necessary to stop the machine, then the butterfly valve 435 will move to its low 50 vacuum position, and the low vacuum pull, which will not draw milk out of the milk tubes 178, will, nevertheless, be sufficient to suck up milk from the nozzles of the heads H and thus clear 55 them of drippings. And, again, upon starting the machine, the butterfly valve, having taken its wide open position and thus applied full vacuum to the filling heads before the rotor gets started, completes the filling and skimming of any bottles which were not completely filled when the 60 full vacuum fell off and the rotor stopped, and does so before such bottles can be lowered away from their filling heads. Thus, the application of full vacuum before the bottle carriers start 65 their travel, insures full filling and skimming of all bottles, under the conditions mentioned.

As before pointed out, when the filled bottles reach the plug 86, and the carriers are exhausted of air, then, were it not for the presence of the adjacent plug 87, the air suddenly exhausted 70 from any one carrier would pass in volume into the groove 81 and might cause the next carrier to jump up, followed, of course, by an immediate downward movement. Thus, possible jiggling or dancing of the carriers is prevented by locat- 75

ing the plug 87 so that as one carrier discharges through port 93, the next carrier will have passed the plug 87 and be beyond the influence of the carrier which is delivering its initial discharge.

5 In this way a smooth operation of the lifters is obtained, and this is accomplished without loss in speed or efficiency in operation.

Thus, it will be seen that when the machine is stopped in the midst of its operation, the drop 10 in the degree of vacuum will prevent milk from being drawn up in the vacuum chamber L to the same extent as would be the case were the vacuum pressure maintained at a high value. In the latter case, that is the case where the vacuum 15 is maintained at a high value, there would be more recirculation than is present where the vacuum is changed to a low value in the way pointed out. By recirculation is meant the flow of milk into the vacuum chamber L and thence 20 back into the main tank E through the trap tank G, and then up again through the bottle into the vacuum chamber and back again into the main tank through the trap tank, and so on over and over, not always the same milk but then some 25 milk always going the rounds. This recirculation is cut down by lowering the value of the vacuum in the way herein described. This is an important feature in the handling of milk and milk products, since they should be disturbed as little as 30 possible in handling in order to maintain their quality in taste and cream line.

Before concluding our disclosure, it should be pointed out that the groove 81 in the stator, which has to do with the operation of the lifters which carry the bottles, may be divided up by plugs in ways differing from that shown. In the illustrative example, the angular distance from plug 84 around to plug 86, during which the lifters are elevated, is considerable. The remaining distance from the plug 86 to the plug 84, during 40 which the lifters are down, is relatively short. Now it is clear that plugs 86 and 84 might be shifted to other positions in the groove 81. Indeed, in practice this very shifting is provided for in order to suit the machine to the filling of 45 different liquids. In the case illustrated, the plugs are arranged about as they should be for the handling of milk. Where the liquid is heavier and more viscous than milk, then it is desirable to shift the plugs 86 and 87 counter-clockwise so as to shorten the filling period and 50 lengthen the exhaust period. This is important because during this exhaust period, the nozzles tend to drip and with the heavier liquids this drip period should be lengthened in order to give 55 the vacuum and syphoning a longer time to clean off the nozzles. Thus, with different liquids, different filling and drip periods are required. Consequently, different positionings of the plugs 60 would be desirable and by such different positionings, the machine may be made to meet the requirements of different kinds of liquids.

It may be noted also that the various parts, except where otherwise noted, are metal, and any desired metal may be used. Preferably, where 65 milk or milk products are being filled into containers, the various parts which engage, or may engage, the milk, are composed of stainless steel or like metal. In some instances chromium plated metal may suffice. Metal which will not spoil the taste of the milk is quite necessary.

Likewise, it should be kept in mind that differences in size of containers, differences in speed of rotation, and differences in the degree of vacuum, are each important. Thus, many different 70

arrangements and operations may be employed, depending upon the condition of service and the judgment of the maker of the machine. Some of these points have been mentioned in our aforesaid Patent No. 1,966,889, and in that patent 5 we have shown several plug arrangements controlled by certain valve control connections. For this reason it does not seem necessary to illustrate more than the one chosen example.

Obviously, in putting our invention into practice many changes and alterations may be made in the details and uses disclosed. Because of these facts, we do not wish to be unduly limited in respect to our claims but aim to cover by their terms all of those alterations and modifications which 15 rightly come within the spirit and scope of the invention.

We claim:

1. A machine of the class described comprising a support, a carrier mounted on said support for 20 rotation about a vertical axis, a main open-topped tank and associated peripheral vacuum chamber secured to said carrier and rotatable with it, an open-topped trap tank mounted within said main tank, a dump tank having a bottom forming 25 a cover for said main and trap tanks and said vacuum chamber to complete the same as enclosures, means for sealing the joints between said cover on the one hand and said tanks and chamber on the other hand, a liquid supply pipe 30 leading from said dump tank to said main tank, a valve for controlling the flow of liquid through said pipe, a float operated by the liquid in said main tank to open and close said valve, filling heads in communication with said vacuum chamber 35 and the lower portion of said main tank, connections for providing vacuum in said vacuum chamber, bottle holders upon said carrier cooperating with said filling heads in the filling of bottles, and valve means operative to pass any 40 liquid collected in said vacuum chamber through said trap tank into said main tank, said dump tank being readily removable from said main and trap tanks and said vacuum chamber to uncover said tanks and chamber, and said trap tank 45 and float being removable from the interior of said main tank and separable from each other, all of said removals and separations enabling the several parts to be cleaned readily and thoroughly. 50

2. A machine of the class described comprising a support, a carrier mounted on said support for rotation about a vertical axis, a main open-topped tank and associated peripheral vacuum chamber secured to said carrier and rotatable 55 with it, an open-topped trap tank mounted within said main tank, a dump tank having a bottom forming a cover for said main and trap tanks and said vacuum chamber to complete the same as enclosures, means for sealing the joints between said cover on the one hand and said tanks and chamber on the other hand, a liquid supply pipe leading from said dump tank to said main tank, said supply pipe being removably secured at its upper end to said dump tank and passing 60 at an intermediate point through the bottom of said trap tank, to which bottom it is firmly and permanently secured, a valve in said main tank at the lower end of said supply pipe for controlling the flow of liquid through said pipe, a 65 float operated by the liquid in said main tank to open and close said valve, filling heads in communication with said vacuum chamber and the lower portion of said main tank, connections for providing vacuum in said vacuum chamber, bot- 70

75

tle holders upon said carrier cooperating with said filling heads in the filling of bottles, and valve means operative to pass any liquid collected in said vacuum chamber through said trap 5 tank into said main tank, said dump tank being readily removable from said main and trap tanks and said vacuum chamber to uncover said tanks and chamber, and said trap tank and supply pipe permanently connected thereto and said float 10 being removable from the interior of said main tank, said trap tank and supply pipe on the one hand and said float on the other hand being readily separable from each other, all of said removals and separations enabling the several parts 15 to be cleaned readily and thoroughly.

3. A machine of the class described including a main tank, a vacuum chamber, an open-topped trap tank, a member for covering said trap tank to complete the same as an enclosure, inlet and 20 outlet valve structures for said trap tank, said closed trap tank and its valves being operative as an air lock between said vacuum chamber and said main tank, a filling head communicating through separate passages with said main tank 25 and said vacuum chamber, and means for operating said valves in sequence to pass any liquid drawn from said head into said vacuum chamber back to said main tank through said trap tank; each of said valve structures comprising a sup- 30 port fixed to said trap tank, a lever removably pivoted upon said support, a flap valve secured to said lever, and a seat about an aperture in a wall of said trap tank; and said valve operating means including a tube through the said wall of 35 said trap tank and a removable actuating rod reciprocable therein to actuate said valve holding levers; said valves, valve levers and operating rod being removable from said trap tank, where- 40 by said trap tank and said associated parts may be readily and thoroughly cleaned.

4. A machine of the class described including a main tank, an open-topped vacuum chamber, an open-topped trap tank, a dump tank, said tanks and chamber being fitted together to provide a substantially air-tight vacuum enclosure and a substantially air-tight trap tank enclosure, and being separable from each other so as to leave all of said tanks and said chamber open for thorough cleaning, removable inlet and outlet 45 valves for said trap tank accessible for removal and cleaning when said trap tank is open, means for alternately opening and closing said valves when the parts are assembled for operation, said inlet valve controlling an opening between said vacuum chamber and said trap tank and said outlet valve controlling an opening between said trap tank and said main tank, a filling head above the level of the bottom of said main tank, a supply connection between said head and the lower part of said main tank, a suction connection 50 between said head and vacuum chamber, and means for periodically presenting bottles to said head for filling with liquid from said main tank, the trap tank and valves operating to return to the main tank any excess liquid drawn into the vacuum chamber. 55

5. A machine of the class described including an open-topped main tank, an open-topped vacuum chamber, an open-topped trap tank in said 60 main tank, a member for covering said main and trap tanks and said vacuum chamber to complete the same as enclosures, inlet and outlet valves for said trap tank, means for alternately opening and closing said valves, said inlet valve 65 controlling an opening between said vacuum

chamber and said trap tank and said outlet valve controlling an opening between said trap tank and said main tank, a filling head above the level of the bottom of said main tank, a supply connection between said head and the lower part of said main tank, a suction connection between said head and vacuum chamber, and means for periodically presenting bottles to said head for filling with liquid from said main tank, the trap tank and valves operating to return to the main 10 tank any excess liquid drawn into the vacuum chamber. 15

6. A machine of the class described comprising a support, a carrier mounted on said support for rotation about a vertical axis, a main open-topped tank and associated peripheral vacuum chamber secured to said carrier and rotatable with it, an open-topped trap tank mounted within said main tank, a dump tank having a bottom forming a cover for said main and trap 20 tanks and said vacuum chamber to complete the same as enclosures, means for sealing the joints between said cover on the one hand and said tanks and chamber on the other hand, a liquid supply pipe leading from said dump tank to said main tank, a valve for controlling the flow of liquid through said pipe, a float operated by the liquid in said main tank to open and close said valve, inlet and outlet valves for said trap tank, means for alternately opening and closing said 25 inlet and outlet valves, said inlet valve controlling an opening between said vacuum chamber and said trap tank and said outlet valve controlling an opening between said trap tank and said main tank, a filling head above the level of the bottom of said main tank, a supply connection between said head and the lower part of said main tank, a suction connection between said head and vacuum chamber, and means for periodically presenting bottles to said head for filling with liquid from said main tank, the trap tank and valves operating to return to the main tank any excess liquid drawn into the vacuum chamber. 30

7. A machine of the class described including a main tank, an open-topped vacuum chamber, an open-topped trap tank, a dump tank, said tanks and chamber being fitted together to provide a substantially air-tight vacuum enclosure and a substantially air-tight trap tank enclosure, and being separable from each other so as to leave all of said tanks and said chamber open 45 for thorough cleaning, a removable inlet valve for said trap tank controlling an opening in a wall of said trap tank above its bottom, said opening leading from said tank to said vacuum chamber, an outlet valve for said trap tank controlling an opening at the bottom of said trap tank, said latter opening leading from said trap tank to said main tank, means for alternately opening and closing said valves, a portion of 50 said means extending within and being carried by said trap tank, said inlet and outlet valves and said portion being accessible for cleaning when said trap tank is open, a filling head above the level of the bottom of said main tank, a supply connection between said head and the lower part of said main tank, a suction connection 55 between said head and vacuum chamber, and means for periodically presenting bottles to said head for filling with liquid from said main tank, a 60 supply connection between said head and the lower part of said main tank, a suction connection between said head and vacuum chamber, and means for periodically presenting bottles to said head for filling with liquid from said main tank. 65

8. A machine of the class described including an open-topped main tank, an open-topped vacuum chamber, an open-topped trap tank in said main tank, a member for covering said main 70 tank, a filling head above the level of the bottom of said main tank, a supply connection between said head and the lower part of said main tank, a suction connection between said head and vacuum chamber, and means for periodically presenting bottles to said head for filling with liquid from said main 75 tank.

and trap tanks and said vacuum chamber to complete the same as enclosures, an inlet valve for said trap tank controlling an opening in a wall of said trap tank above its bottom, said opening leading from said tank to said vacuum chamber, an outlet valve for said trap tank controlling an opening at the bottom of said trap tank, said latter opening leading from said trap tank to said main tank, means for alternately opening and closing said valves, a filling head above the level of the bottom of said main tank, a supply connection between said head and the lower part of said main tank, a suction connection between said head and vacuum chamber, and means for periodically presenting bottles to said head for filling with liquid from said main tank, the trap tank and valves operating to return to the main tank any excess liquid drawn into the vacuum chamber.

20. 9. A machine of the class described comprising a support, a carrier mounted on said support for rotation about a vertical axis, a main open-topped tank and associated peripheral vacuum chamber secured to said carrier and rotatable with it, an open-topped trap tank mounted within said main tank, a dump tank having a bottom forming a cover for said main and trap tanks and said vacuum chamber to complete the same as enclosures, means for sealing the joints between said cover on the one hand and said tanks and chamber on the other hand, a liquid supply pipe leading from said dump tank to said main tank, a valve for controlling the flow of liquid through said pipe, a float operated by the liquid in said main tank to open and close said valve, an inlet valve for said trap tank controlling an opening in a wall of said trap tank above its bottom, said opening leading from said tank to said vacuum chamber, an outlet valve for said trap tank controlling an opening at the bottom of said trap tank, said latter opening leading from said trap tank to said main tank, means for alternately opening and closing said inlet and outlet valves, a filling head above the level of the bottom of said main tank, a supply connection between said head and the lower part of said main tank, a suction connection between said head and vacuum chamber, and means for periodically presenting bottles to said head for filling with liquid from said main tank, the trap tank and valves operating to return to the main tank any excess liquid drawn into the vacuum chamber.

10. A machine of the class described, comprising a base, a carrier rotatable on said base, a main tank, a vacuum chamber, a trap tank, inlet and outlet valves cooperating with said trap tank, said tanks and chamber and valves being mounted upon and movable with said carrier, filling heads also supported by said carrier and being in communication with said main tank and said vacuum chamber and operative to draw liquid from said tank into bottles properly presented to said heads, a pneumatically operated device for use in operating said inlet and outlet valves, said device including a valve actuating member in association with an enclosed air chamber, and valve means having passages in communication with said air chamber and with atmosphere and with a compressed air supply, said valve means being responsive to movements of said carrier upon said base, to vary the air connections with said device to operate the same, thereby to properly operate said inlet and outlet valves.

11. A machine of the class described, comprising a base having an upper bearing surface,

a carrier rotatable on said base and having an under bearing surface cooperating with the said upper bearing surface of said base, a main tank, a vacuum chamber, a trap tank and cooperating inlet and outlet valves, said tanks and chamber and valves being supported by and rotatable with said carrier, filling heads carried by said carrier and in direct communication with said main tank and said vacuum chamber and operative to draw liquid from said tank into bottles presented to said heads, a pneumatically operated device for use in actuating said inlet and outlet valves, said device including a reciprocating member in association with an air chamber, said air chamber being in communication with a passage terminating in a port on the under bearing surface of said carrier, said base having a grooved passageway on its upper bearing surface for cooperation with said port, means for dividing said passageway into segments, and means for variously connecting said segmental passages to a compressed air supply and to atmosphere to variously operate said actuating device and thereby properly operate said valves.

12. A machine of the class described, comprising a base having an upper bearing surface, a carrier rotatable on said base and having an under bearing surface cooperating with the said upper bearing surface of said base, a main tank, a vacuum chamber, a trap tank and cooperating inlet and outlet valves, said tanks and chamber and valves being supported by and rotatable with said carrier, filling heads carried by said carrier and in direct communication with said main tank and said vacuum chamber and operative to draw liquid from said tank into bottles presented to said heads, a pneumatically operated device for actuating said valves, said device comprising a reciprocating member cooperating with the vacuum to close the inlet valve and open the outlet valve upon one movement and to open the former and close the latter upon the other movement, an air chamber forming part of said device and having a wall movable under air pressure to bring about movement of said reciprocating member in one direction, said member moving in the opposite direction upon the withdrawal of compressed air from said air chamber, said air chamber being in communication with a passage terminating in a port on the under bearing surface of said carrier, said base having a grooved passageway on its upper bearing surface for cooperation with said port, means for dividing said passageway into segments, and means for variously connecting said segmental passages to a compressed air supply and to atmosphere to variously operate said actuating device and thereby properly operate said valves.

13. A machine of the class described, comprising a base, a carrier, bottle filling heads and pneumatically operated supports on said carrier and movable with it, said heads and supports being in vertical alinement, one head with each support, said supports having in each case a bottle engaging member above an air chamber, said chamber being in communication with passages terminating in ports on the under bearing surface of said carrier, one port for each air chamber, said base having a grooved passageway on its upper bearing surface for cooperation with said ports, means for dividing said passageway into four segments, a short pressure segment followed by a long pressure segment, followed by a short atmospheric segment, followed by a long

atmospheric segment, the segments being encountered in the order named by each port as it advances, and means for supplying compressed air to said pressure segments and atmospheric air to said atmospheric segments.

14. A machine of the class described, comprising a base, a carrier, bottle filling heads and pneumatically operated supports on said carrier and movable with it, said heads and supports being in vertical alinement, one head with each support, said supports having in each case a bottle engaging member above an air chamber, said chamber being in communication with passages terminating in ports on the under bearing surface of said carrier, one port for each air chamber, said base having a grooved passageway on its upper bearing surface for cooperation with said ports, means for dividing said passageway into four segments, a short pressure segment followed by a long pressure segment, followed by a short atmospheric segment, followed by a long atmospheric segment, the segments being encountered in the order named by each port as it advances, means for supplying compressed air to said pressure segments and atmospheric air to said atmospheric segments, and means for supplying lubricating oil to said short pressure segment whereby each of said air chambers sucks up lubricant for its interior as the corresponding port passes over said first pressure segment.

15. A machine of the class described comprising a base, a carrier mounted for rotation on said base, upright standards supported by said carrier, cylindrical bottle lifting members each having a closed end constituting the bottle support and a skirted portion fitting over said standard, suitable packing about the upper end of each standard engaging the interior of the cylindrical wall of the associated lifting member, the interior of the lifting member above the standard constituting in each case an air chamber, a stem extending downward from the closed end of each lifting member into a cylindrical well in the associated standard, a spring around each stem acting to lower the associated lifting member when unrestrained by the air within said member, said standard in each instance having an air supply passage communicating with the interior of the lifting member above the standard and terminating in a port on the under bearing surface of said carrier, said base having a grooved passageway on its upper bearing surface for cooperation with said ports, means for dividing said passageway into four segments, a short pressure segment followed by a long pressure segment, followed by a short atmospheric segment, followed by a long atmospheric segment, the segments being encountered in the order named by each port as it advances, and means for supplying compressed air to said pressure segments and atmospheric air to said atmospheric segments.

16. A machine of the class described comprising a base, a carrier mounted for rotation on said base, upright standards supported by said carrier, cylindrical bottle lifting members each having a closed end constituting the bottle support and a skirted portion fitting over said standard, suitable packing about the upper end of each standard engaging the interior of the cylindrical wall of the associated lifting member, the interior of the lifting member above the standard constituting in each case an air chamber, a stem extending downward from the closed

end of each lifting member into a cylindrical well in the associated standard, a spring around each stem acting to lower the associated lifting member when unrestrained by the air within said member, said standard in each instance having an air supply passage communicating with the interior of the lifting member above the standard and terminating in a port on the under bearing surface of said carrier, said base having a grooved passageway on its upper bearing surface for cooperation with said ports, means for dividing said passageway into four segments, a short pressure segment followed by a long pressure segment, followed by a short atmospheric segment, followed by a long atmospheric segment, the segments being encountered in the order named by each port as it advances, means for supplying compressed air to said pressure segments and atmospheric air to said atmospheric segments, and means for supplying lubricating oil to said short pressure segment whereby each of said air chambers sucks up lubricant for its interior as the corresponding port passes over said first pressure segment.

17. A machine of the class described including a filling head having an outer receptacle-engaging portion and a central nozzle portion, said head serving to close the receptacle with an air tight seal, a liquid container adapted to hold liquid at a level below the level of said nozzle, a vacuum chamber having its lowest point above said liquid level, a vacuum passage extending from a vacuum port in said nozzle to said vacuum chamber, a supply passage extending from said liquid container to a supply port in said nozzle, said passage to said container terminating below the liquid level therein, automatic means for periodically passing liquid drawn by vacuum from said container through said head and receptacle into said vacuum chamber, back into said container, said circuit constituting a path for liquid recirculation, means for producing a vacuum in said vacuum chamber sufficient to cause liquid to flow into the positioned receptacle and fill the same and the surplus to pass on into the vacuum chamber, and means for lowering said vacuum to render it insufficient to raise the liquid to the receptacle filling point while still remaining sufficient to withdraw liquid from said vacuum passage into said vacuum chamber to clear said nozzle from drippings.

18. A machine of the class described including a filling head having an outer receptacle-engaging portion and a central nozzle portion, said head serving to close the receptacle with an air tight seal, a liquid container adapted to hold liquid at a level below the level of said nozzle, a vacuum chamber having its lowest point above said liquid level, a vacuum passage extending from a vacuum port in said nozzle to said vacuum chamber, a supply passage extending from said liquid container to a supply port in said nozzle, said passage to said container terminating below the liquid level therein, automatic means for periodically passing liquid drawn by vacuum from said container through said head and receptacle into said vacuum chamber, back into said container, said circuit constituting a path for liquid recirculation, a suction pump, a channel between said vacuum chamber and pump, and means for varying the opening of said channel to vary the vacuum in said vacuum chamber, both to fill presented receptacles and take surplus up into the vacuum chamber.

and to clean out said head without filling a receptacle.

19. A machine of the class described including a filling head having an outer receptacle-engaging portion and a central nozzle portion, said head serving to close the receptacle with an air tight seal, a liquid container adapted to hold liquid at a level below the level of said nozzle, a vacuum chamber having its lowest point above said liquid level, a vacuum passage extending from a vacuum port in said nozzle to said vacuum chamber, a supply passage extending from said liquid container to a supply port in said nozzle, said passage to said container terminating below the liquid level therein, automatic means for periodically passing liquid drawn by vacuum from said container through said head and receptacle into said vacuum chamber, back into said container, said circuit constituting a path for liquid recirculation, a suction pump, a channel between said vacuum chamber and said pump, a butterfly valve in said channel having a small opening through its blade, said valve when open providing a relatively large passage through said channel and when closed a relatively small passage determined by said small opening, the relatively large passage providing, when said pump is operating and a receptacle is properly presented to said head, a vacuum pull sufficient to draw liquid up into said vacuum chamber, and the relatively small passage providing under like conditions a vacuum pull of less power, sufficient only to draw liquid part way up to said head and operative, when a receptacle is not presented to the head, to clear the nozzle of drippings of liquid left from a previous filling.

20. A machine of the class described including a filling head having an outer receptacle-engaging portion and a central nozzle portion, said head serving to close the receptacle with an air tight seal, a liquid container adapted to hold liquid at a level below the level of said nozzle, a vacuum chamber having its lowest point above said liquid level, a vacuum passage extending from a vacuum port in said nozzle to said vacuum chamber, a supply passage extending from said liquid container to a supply port in said nozzle, said passage to said container terminating below the liquid level therein, automatic means for periodically passing liquid drawn by vacuum from said container through said head and receptacle into said vacuum chamber, back into said container, said circuit constituting a path for liquid recirculation, a support for the receptacle, means for rotating said head and support, means for bringing said head and receptacle together for filling, means for producing a vacuum in said vacuum chamber sufficient to cause liquid to flow from said liquid container into the receptacle and fill it, means for lowering said vacuum to render the same insufficient to raise the liquid to the receptacle filling point but sufficient to clear said nozzle from drippings by sucking surplus liquid from said head into said vacuum chamber, and means for stopping the rotation of said head and support only after said vacuum lowering means has been operated.

21. A machine of the class described comprising a support, a rotary carrier mounted on said support, an electric motor and gearing for rotating said carrier, a switch for said motor, a control device for said switch, vacuum mechanism for filling liquid into receptacles carried by

said carrier; said mechanism including a main supply tank, a vacuum chamber, and filling heads, each of said heads connecting through separate passages with said main tank and vacuum chamber and operative under a normal vacuum pull to draw liquid from said main tank into receptacles properly presented to said head for filling and operative under a reduced vacuum pull merely to clean said head of drippings without filling receptacles; a vacuum supply for said vacuum chamber, a control device for varying said vacuum supply to give said normal vacuum pull and said reduced vacuum pull, and means for operating said vacuum control device and said switch control device successively in the order named with a time interval intervening in order to insure complete filling of any partially filled receptacles, if there be such, before starting the carrier.

22. A machine of the class described comprising a support, a rotary carrier mounted on said support, an electric motor and gearing for rotating said carrier, a switch for said motor, a control device for said switch, vacuum mechanism for filling liquid into receptacles carried by said carrier; said mechanism including a main supply tank, a vacuum chamber, and filling heads, each of said heads connecting through separate passages with said main tank and vacuum chamber and operative under a normal vacuum pull to draw liquid from said main tank into receptacles properly presented to said head for filling and operative under a reduced vacuum pull merely to clear said head of drippings without filling receptacles; a suction pump, a vacuum channel extending from said vacuum chamber to said pump, means in said channel for varying the same to provide said normal vacuum pull and said reduced vacuum pull, a control device for said vacuum varying means, a remote control device having running and stopping positions, and means including connections from said remote control device to said switch control device and to said vacuum control device whereby the movement of said remote control device from its stopping position to its running position first operates said vacuum control to insure complete filling of any partially filled receptacles, if there be such, and then after a time interval operates said switch control to start said carrier.

23. A machine of the class described comprising a support, a rotary carrier mounted on said support, an electric motor and gearing for rotating said carrier, a switch for said motor, a pneumatically operated device for actuating said switch, a vacuum mechanism for filling liquid into receptacles carried by said carrier; said mechanism including a main supply tank, a vacuum chamber, and filling heads, each of said heads connecting through separate passages with said main tank and vacuum chamber and operative under a normal vacuum pull to draw liquid from said main tank into receptacles properly presented to said head for filling and operative under a reduced vacuum pull merely to clean said head of drippings without filling receptacles; a vacuum supply for said vacuum chamber, a valve for varying said vacuum supply to give said normal vacuum pull and said reduced vacuum pull, a pneumatically operated device for actuating said vacuum varying valve, a control valve, tubular connections extending from said control valve to said pneumatically operated devices, a compressed air supply, said control valve and tubular connections serving in one position of

- 5 said control valve to connect said pneumatically operated devices to said compressed air supply and in another position of said valve to exhaust said devices, and means for retarding the initial operation of said switch operating device so as to follow after an interval the initial operation of said valve operating device following the connection of said devices to said compressed air supply whereby the restoration of the vacuum pull to normal completes the filling of partially filled 10 receptacles, should there be such, before the carrier begins to move them toward unseating position.
- 15 24. A machine of the class described comprising a support, a rotary carrier mounted on said support, an electric motor and gearing for rotating said carrier, a switch for said motor, a pneumatically operated device for actuating said switch, a vacuum mechanism for filling liquid into receptacles carried by said carrier; said mechanism including a main supply tank, a vacuum chamber, and filling heads, each of said heads connecting through separate passages with said main tank and vacuum chamber and operative under a normal vacuum pull to draw liquid from said main tank into receptacles properly presented to said head for filling and operative under a reduced vacuum pull merely to clean said head of drippings without filling receptacles; a 20 suction pump, a vacuum channel extending from said vacuum chamber to said pump, a butterfly valve in said channel for varying the flow of air therethrough to provide in one position said normal vacuum pull and in another position said reduced vacuum pull, a pneumatically operated device for moving said butterfly valve into said positions, a control valve, tubular connections extending from said control valve to said pneumatically operated devices, a compressed air supply, said control valve and tubular connections serving in one position of said control valve to connect said pneumatically operated devices to said compressed air supply and in another position of said valve to exhaust said devices, and means for retarding the initial operation of said switch operating device so as to follow after an interval the initial operation of said valve operating device following the connection of said devices to said compressed air supply whereby the restoration of the vacuum pull to normal completes the filling of partially filled receptacles, should there be such, before the carrier begins to move them toward unseating position.
- 25 25. A machine of the class described including a main tank, a vacuum chamber, a filling head communicating through separate passages with said main tank and vacuum chamber and operative under the vacuum pull to draw liquid from said main tank into bottles successively presented to said head for filling, a trap tank positioned to receive liquid drawn into said vacuum chamber and pass it into said main tank, a liquid inlet valve controlling an opening between said vacuum chamber and said trap tank, a liquid outlet valve controlling an opening between the lower part of said trap tank and said main tank, cyclic means for successively operating said liquid controlling valves to pass liquid through said trap tank, means operative as a by-pass to said inlet valve to equalize the vacuum pressures in said vacuum chamber and said trap tank subsequent to the closing of said outlet valve and prior to the opening of said inlet valve, and other means operating alternatively therewith to equalize the 70 air pressures in said trap tank and said main

tank following the closing of said inlet valve and prior to the opening of said outlet valve, whereby the mixing of air with the liquid as it passes into and out of said trap tank will be a minimum.

26. A machine of the class described including a main tank, a vacuum chamber, a filling head communicating through separate passages with said main tank and vacuum chamber and operative under the vacuum pull to draw liquid from said main tank into bottles successively presented to said head for filling, a trap tank positioned to receive liquid drawn into said vacuum chamber and pass it into said main tank, a liquid inlet valve controlling an opening between said vacuum chamber and said trap tank, a liquid outlet valve controlling an opening between the lower part of said trap tank and said main tank, said valves being adapted to operate successively to pass liquid through said trap tank, a reciprocating member and cooperating mountings for shifting said valves, the operation being a closing of the inlet valve and an opening of the outlet valve for one position of said reciprocating member and a closing of the outlet valve and an opening of the inlet valve for a second position of said reciprocating member, a leak opening between said vacuum chamber and said trap tank to equalize the vacuum pressures therein upon the closing of said outlet valve and prior to the opening of said inlet valve, and means associated with said reciprocating member to equalize the air pressures in said trap tank and said main tank following the closing of said inlet valve and prior to the opening of said outlet valve, whereby the flow of equalizing air into said trap tank will occur without mixing with the liquid passing through the trap tank.

27. A machine of the class described comprising a vacuum chamber, a liquid supply tank, a nozzle having vacuum and liquid delivering ports at a level above that of the liquid in said supply tank, suitable vacuum and supply tank connections to said nozzle ports, respectively, packing around said nozzle, means for bringing said packing and the mouth of a bottle together with the vacuum and liquid openings of said nozzle communicating with the interior of said bottle, means for separating said packing and bottle, a trap tank, means for periodically equalizing the air pressure in said trap tank and vacuum chamber, means for periodically equalizing the air pressure in said trap tank and supply tank, and means operating in timed relation with said equalizing means to flow liquid from said vacuum chamber into said trap tank and then from said trap tank into said supply tank.

28. A machine of the class described including a main tank, a vacuum chamber, a filling head communicating through separate passages with said main tank and vacuum chamber and operative under the vacuum pull to draw liquid from said main tank into bottles successively presented to said head for filling, a trap tank positioned to receive liquid drawn into said vacuum chamber and pass it into said main tank, a liquid inlet valve controlling an opening between said vacuum chamber and said trap tank, a liquid outlet valve controlling an opening between said trap tank and said main tank, means for successively operating said inlet and outlet valves to pass liquid through said trap tank, and means operative as a by-pass to said inlet valve to equalize the vacuum pressures in said vacuum chamber and said trap tank subsequent to the closing of said outlet valve and prior to the opening of said inlet valve, and other means operating alternatively therewith to equalize the air pressures in said trap tank and said main tank.

closing of said outlet valve and prior to the opening of said inlet valve.

29. A machine of the class described including a main tank, a vacuum chamber, a filling head communicating through separate passages with said main tank and vacuum chamber and operative under the vacuum pull to draw liquid from said main tank into bottles successively presented to said head for filling, a trap tank positioned to receive liquid drawn into said vacuum chamber and pass it into said main tank, a liquid inlet valve controlling an opening between said vacuum chamber and said trap tank, a liquid outlet valve controlling an opening between said trap tank and said main tank, means for successively operating said inlet and outlet valves to pass liquid through said trap tank, and means operative to equalize the air pressures in said trap tank and said main tank following the closing of said inlet valve and prior to the opening of said outlet valve.

30. A machine of the class described comprising a support, a rotary carrier mounted on said support, an electric motor and gearing for rotat-
25 ing said carrier, an electric switch for said motor, vacuum mechanism for filling liquid into receptacles carried by said carrier; said mechanism including a main supply tank, a vacuum chamber, and filling heads, each of said heads
30 connecting through separate passages with said main tank and vacuum chamber and operative under a normal vacuum pull to draw liquid from said main tank into receptacles properly presented to said head for filling, and operative under a reduced vacuum pull merely to clean said head of drippings without filling receptacles; a vacuum supply for said vacuum chamber, a control device for varying said vacuum supply to give said normal vacuum pull and said reduced vacuum pull, and means for operating said electric switch and said vacuum control device in a definite order and only in that order.

31. A machine of the class described comprising a support, a rotary carrier mounted on said support, lifters for the bottles upon said carrier, a liquid supply tank, a vacuum chamber and filling heads; said tank, chamber and heads being rotatable on said support in synchronism with said carrier and said heads being in vertical alignment with said lifters respectively, each said head connecting through separate passages with said supply tank and vacuum chamber and operative under a normal vacuum pull to draw liquid from said supply tank through the associated bottle into said vacuum chamber, the bottle being thereby filled and the surplus liquid taken into said vacuum chamber, and operative under a reduced vacuum pull merely to clear the head of drippings; a trap tank, means tending to equalize the air pressure in said trap tank and vacuum chamber, additional means responsive to the rotation of said carrier to equalize the air pressure in said trap tank and said supply tank, valve means operating in timed relation to the operations of said equalizing means to flow liquid from said vacuum chamber into said trap tank and then from said trap tank into said supply tank, a vacuum supply for said vacuum chamber, and a control device for varying said vacuum supply to give said normal vacuum pull and said reduced vacuum pull, the circuit for the liquid from said supply tank through a positioned bottle, the vacuum chamber and the trap tank back to said supply tank constituting a

path for liquid recirculation, said path being maintained when a bottle is in filling position and a normal vacuum pull is being applied.

32. A machine of the class described includ-
5 ing a series of filling heads, each having an outer receptacle-engaging portion and a central nozzle portion, said head serving in each instance to close a receptacle with which it is associated with an airtight seal, a liquid container adapted to hold liquid at a level below the level of said nozzles, a vacuum chamber having its lowest point above the level of the liquid in said container, a vacuum passage extending from a vacuum port in each said nozzle to said vacuum chamber, a supply passage extending from said liquid container to a supply port in each said nozzle, said passages to said container from said supply ports terminating below the level of the liquid in said container, a support; said heads, liquid container, vacuum chamber and associated 10 passages all rotatable on said support as a single unit; means operating to produce a full vacuum in said vacuum chamber, said full vacuum being sufficient to draw the liquid out of said container up through said heads and receptacles 15 into said vacuum chamber as the heads and receptacles present themselves at filling positions, means for periodically locking liquid caught in said vacuum chamber through an intervening locking tank into said container, said locking 20 means being dependent for its operation upon the rotation of the aforesaid parts constituting said single unit upon said support, said paths from said container up through said heads and associated receptacles into said vacuum chamber 25 and thence back to said container through said transferring means constituting recirculating circuits, said paths being established periodically as the machine operates and receptacles are presented for filling, and means for changing the vacuum in said vacuum chamber to exert 30 a low vacuum pull, said low pull being insufficient to draw liquid from said container as far as said heads but nevertheless operating to draw liquid from the nozzles of said heads whenever 35 the same are not engaged by receptacles and thus clear them of drippings resulting from previous use.

33. A machine for filling liquid into upright bottles by suction comprising a supply tank below the bottle filling level, said supply tank being open to atmospheric pressure, a vacuum chamber for supplying the filling suction, means under the control of the bottles for utilizing the suction to start and stop the flow of liquid from said supply tank into the bottles and to some extent into said vacuum chamber, a trap tank, air conducting means for establishing communication between said vacuum chamber and trap tank on the one hand and between said trap tank and atmosphere on the other hand, liquid inlet and outlet means for establishing communication between the vacuum chamber and trap tank on the one hand and between the trap tank and the supply tank on the other hand, said liquid inlet and outlet means communicating with said trap tank at points below those at which said air conducting means communicate therewith and providing paths for liquid which are independent of the paths for air provided by said air conducting means, means for periodically utilizing said air conducting means to equalize the air pressure in said vacuum chamber and trap tank on the one hand and to reduce the pressure in said trap tank to that of atmosphere 75

on the other hand, and means operating in timed relation with said air equalizing means to utilize said liquid inlet and outlet means to cause liquid to pass from said vacuum chamber into said trap tank and then from said trap tank into 5 said supply tank.

34. A machine of the class described comprising a liquid supply tank open to atmospheric pressure, delivering nozzles, tubular connections between said nozzles and said supply tank, a 10 vacuum chamber, tubular connections between said vacuum chamber and said nozzles, lifters for the bottles whereby the open ends of the bottles may be brought into operative relation 15 with the respective nozzles, means for exhausting the air from said vacuum chamber to produce a vacuum in said chamber, nozzles, bottles and connections, whereby the liquid is drawn into the bottles by suction and surpluses of liquid 20 are drawn into said vacuum chamber, a trap tank, air conducting means for establishing communication between said vacuum chamber and trap tank on the one hand and between said trap tank and atmosphere on the other hand, liquid 25 inlet and outlet means for establishing communication between the vacuum chamber and trap tank on the one hand and between the trap tank and the supply tank on the other hand, said liquid inlet and outlet means communicating with 30 said trap tank at points below those at which said air conducting means communicate therewith and providing paths for liquid which are independent of the paths for air provided by 35 said air conducting means, means for periodically utilizing said air conducting means to equalize the air pressure in said vacuum chamber and trap tank on the one hand and to reduce the

pressure in said trap tank to that of atmosphere on the other hand, and means operating in timed relation with said air equalizing means to utilize said liquid inlet and outlet means to cause liquid to pass from said vacuum chamber into said trap tank and then from said trap tank into said supply tank. 5

35. In a machine of the class described, the combination of a filling head having a nozzle adapted to cooperate with the mouth of a bottle to be filled, a vacuum chamber, means for evacuating said chamber, a liquid supply chamber at a level below said head, said head being provided with continuously open vacuum and liquid passages communicating with said vacuum and supply chambers respectively and terminating in vacuum and supply ports adapted to enter the open mouth of the bottle to be filled, said parts operating to fill the bottle by producing a vacuum therein, said nozzle having a substantially horizontal terminal face forming a flat apex by which the level of the liquid in the filled bottle is determined, an adjacent inclined face bounding said apex and receding therefrom outward and toward said head, said vacuum port being located in said apex face and said supply port being located in said inclined face, the periphery of said apex face being at all points practically the same distance from said vacuum port to insure a substantially equal pull all around 20 said port in carrying off surplus liquid after filling the bottle, and a cushion around said nozzle near its lower end for engaging the bottle top and forming a tight seal with the same during the filling of the bottle. 25
